UNITED STATES PATENT OFFICE.

ERNEST AUGUST FALLER, OF NEW YORK, N. Y., ASSIGNOR, BY MESNE ASSIGNMENTS,
TO THE NORTH ELECTRIC MANUFACTURING COMPANY.

SELF-ACTING TELEPHONE SYSTEM.

Application filed July 28, 1904. Serial No. 218,490.

To all whom it may concern:

Be it known that I, ERNEST A. FALLER, a citizen of the German Empire, residing at No. 203 West 103rd Street, New York, 5 in the county of New York and State of New York, have invented certain new and useful Improvements in Self-Acting Telephone Systems, of which the following is a specification.

10 The present system refers to a self-acting telephone exchange, by which is meant an apparatus using strictly mechanical means for the purpose of practically duplicating all of the functions of the human operator 15 in a manual telephone exchange now in use in nearly all existing telephone plants. It is a mechanical operator or machine-telephone in contradistinction to the greater part of automatic telephone systems so far devised, which are not more than an aggregation of identical individual switches, each one complete in itself and relying in its 20 operation upon motor-magnets or their equivalents, whereas the present system uses, 25 wherever possible, an extraneous source of power, preferably mechanical power, to perform the switching act proper.

One of the objects of the invention is, and the same is thought to be broadly new, to 30 divide the operation of the machine into two distinct groups, one of the same confined to the receiving of an electrical signal, and the second to the act of actually performing the switching operation, the two 35 distinct operations always timely following each other, and the switching operation always depending upon the preceding signal-receiving act.

30 The method of sending and receiving variable signals, employed in the present invention, consists in dividing an entire electrical signal into groups or sets of separate variable signals, in simultaneously transmitting the variable signals forming a group 45 or set, and in successively transmitting the groups or sets forming the entire electrical signal. The apparatus for sending an entire electrical signal comprising a plurality of variable signals from a subscriber's station to a telephone exchange is described and claimed in the U. S. patent to Ernest A. Faller, No. 757,030, dated April 12, 1904.

The present system is similar to a plug-and cord-system, that is, it employs the

equivalents of subscribers' jacks and loop- or cord-circuits with plugs, such as employed at present in any manual system; one form 55 of such a system employing automatically operated means for uniting any two of the line-terminals with each other through one of said loop-circuits is described and claimed in the U. S. patent to Ernest A. Faller, No. 60 686,892, dated November 19, 1901.

The present invention, furthermore, uses the so-called percentage system, now well known in the art, in which the cord-circuits, or their equivalents, and the means for uniting any two subscribers connected to the exchange section through one of the cord-circuits, are provided in an exact proportion to the maximum number of conversations expected to take place at one and the same 70 time, which number, as a rule, does not exceed a small fraction of the total number of subscribers connected to the exchange section.

The recognition of the principle of a percentage exchange in connection with that of the division of an entire exchange into exchange-sections, the use of the plug- and cord-system, and the division of the entire signal into groups or sets of variable signals, undoubtedly simplifies the problem of automatically connecting telephone subscribers and eliminates the necessity, so prevalent in other automatic telephone systems, of employing a large number of complex 80 apparatus individual to each subscriber, which practically offsets the advantage gained by the use of an automatic system instead of a manual system.

It is one of the objects of the present invention to avoid complex apparatus, individual to each subscriber, and intended for the exclusive use of one subscriber. The only apparatus to be provided in great numbers, i. e. the same number as there are subscribers 95 connected to the exchange, is a simple relay of any commercial form for each subscriber, and some stationary parts, such as contacts and line-terminals. The only moving part in the entire exchange, individual to each 100 subscriber is the armature of this relay.

Referring now to that part of the entire system which is intended for the common use of a group of subscribers, generally one hundred, it may be stated that its functions, 105 with the single exception of receiving the

signal, correspond practically to each and every act performed by the operator or operators in establishing connection in a manual exchange.

As stated hereinbefore, the present invention is based upon a percentage exchange, which percentage in a manual exchange varies between five to twelve per hundred, and in the present case, the largest number ever required in manual practice is taken and twelve link circuits are provided, which would enable twenty-four subscribers out of each one hundred, to hold communication with each other simultaneously. A number of plugs or traveling terminals corresponding to the number of link circuits are provided, but, of course, take a different shape in the present invention than in a manual exchange, nevertheless practically answering the very same purpose.

The equivalent of the human operator in the manual exchange is represented in the present invention by the power-driven machine part of the system which is provided only once for each one hundred subscribers, whereas other systems provide an apparatus of comparatively similar complexity, once for each subscriber. In employing such operating means which are common to all subscribers connected to the exchange section, it is absolutely necessary to provide a device which will prevent simultaneous calls from interfering with each other. In the present specification I have called this device an allotter, and it serves the purpose of causing the calls of the various subscribers connected to the exchange to go through the same in sequence notwithstanding the fact that several calls may have been originated at one and the same instant. As it is essential to perform all necessary operations as quickly as possible, the duration of operation of this part must not be lost sight of. In older machines of this character, such for example as shown in U. S. Patent No. 686,892, where means were employed to cause a succession and predetermined rotation of the calling subscribers in using the common operating means, four revolutions per minute were about the limit of speed which could be employed. During each revolution, contacts were made successively with at least one hundred points, one for each subscriber connected to the exchange, and the actual contact-time for each call coming in, could not be made less than .075 of a second. This was the practical limit, and a greater speed could not be used without having the contact time of such short duration that it was no longer capable of performing its function, that is, energizing the magnet and thereby causing attraction of its armature.

In the present invention no movable contacts are utilized in the same manner, and

all the contacts which are relied upon for the purpose of producing succession and rotation of the calling subscribers, are at rest at the moment when they are called upon to do their work, which permits the operation of those parts of the mechanism which perform this function, at a speed of between 200 and 250 revolutions per minute, or nearly fifty times as great as the speed in older machines. It is thought that this system of preventing interference and causing succession and rotation of the calling subscribers is not only broadly new, but appears to be the only system to accomplish the desired results without appreciable loss of time.

It has been stated that the entire exchange is divided into exchange-sections, and, therefore, it becomes necessary to provide means for interconnection or trunking between the sections. This part of the invention bears a great resemblance to the so-called "express system," in which the entire switching act is subdivided into three distinct operations, which, in a manual board, consist:—

1. In connecting by the first operator the calling subscriber's line to the board of an auxiliary or intermediate operator;
2. In selecting a trunk line by that auxiliary operator which leads to the section to which the called subscriber is connected, and
3. After the operator at this exchange-section has instructed the auxiliary operator what trunk-line to select, in completing the connection between said selected trunk-line with the line-terminal of the called subscriber.

In the present invention there are provided equivalents for each of the three operators, which, although separate, are of similar construction and perform practically the identical function of the three human operators in the so-called "express system".

In the present invention those three sets of operating mechanism are named, respectively, and in the order of their use: the "originator", the "pilot" and the "terminator". All subscribers' lines connected to an exchange section end in stationary contacts at the originator as well as at the terminator, the originator contacts are used for "calling", and the terminator contacts for "being called". The office of each of the three groups of mechanism is, to bring the equivalents of plugs in the manual exchange, which in the present invention are called "shuttles", into contact with the respective subscriber's line- or trunk line-terminals. That is to say, the originator, after having selected an idle link circuit from the twelve link circuits provided in the system, lifts the originator shuttle of the selected link circuit into contact with the line-terminal of the calling subscriber,

and through the link circuit of which this shuttle forms one end, the calling subscriber's line is extended into the pilot, where it terminates in a similar shuttle.

- 5 At the pilot, a number of trunk terminals are provided, connected to trunk lines radiating to the terminators of all exchange sections forming the entire telephone system. It follows, therefore, that one or more of 10 these trunk lines will lead to the terminator of the exchange section of which the pilot referred to is a part. The pilot lifts the shuttle of this extended subscriber's line into contact with the selected trunk-line, 15 and thereby extends the subscriber's line to the terminator of that exchange-section to which the called subscriber is connected. The terminator finally lifts the shuttle, which now forms the end of the extended 20 line of the calling subscriber, into contact with the line-terminal of the called subscriber, and, thereby, completes the connection between the calling subscriber and the called subscriber.
- 25 In the present invention, provision is made such that after the first part of the entire signal has been received at the exchange, no other part can be received until the switching operation, corresponding 30 to the preceding part of the signal, has been actually completed.

General operation of the self-acting exchange.

- 35 The operation of a self-acting telephone exchange constructed in accordance with the present invention, and the various steps in accomplishing connection between two subscribers through the exchange are as follows:—

40 When the calling subscriber has set his sender to the call-number of the called subscriber, has turned the knob of the sender and released the same, his sender, which is 45 normally off ground, becomes grounded. The immediate result of grounding the subscriber's sender is the actuation of certain mechanism at the originator of the exchange section with which the calling subscriber is 50 connected, which results in connecting an idle originator-shuttle—as stated hereinbefore, the equivalent of the answering plug in a manual exchange—with that set of line-terminals of the originator, belonging 55 to the calling subscriber.

An interference-preventing mechanism is 60 provided at the originator of the self-acting exchange, which holds—stores, as it were—the coming-in call until any preceding call has been disposed of, should the originator be engaged in establishing connection for a previous caller. The originator-shuttle having thus been placed into connection with the calling subscriber's line-terminal, the calling line is now extended

to that shuttle in the pilot of the same exchange-section which forms the other terminal of the link circuit selected by the originator, of which the originator-shuttle forms one terminal, and certain conditions 70 are brought about in the pilot which result in electrical connections, tending toward the releasing of the calling subscriber's sender and the transmission to and recording at the pilot, of the "group-signal", i. e., the 75 thousand and hundred numeral of the called subscriber's call-number, which group-signal identifies that exchange-section of the entire system with which the called subscriber is connected. 80

As soon as this group-signal is received at the pilot, certain mechanism cause a "busy-test" among the several trunk-lines available between the pilot of the exchange-section of the calling subscriber and that 85 exchange-section with which the called subscriber is connected. If any of the trunk-lines are idle, the machine automatically determines which one of the idle trunks should be given to the calling subscriber. 90

The pilot now connects the pilot-shuttle mentioned with the trunk-terminals selected and, thereby, continues the line already established from the calling subscriber, to that exchange-section with which the called 95 subscriber is connected.

Similar to the extension of the calling subscriber's line from the originator to the pilot, this line now terminates at one of the terminator-shuttles of the exchange-section 100 with which the called subscriber is connected, and certain electrical conditions are brought about in said terminator which result in a second release of the subscriber's sender, and the transmission to and recording 105 at the terminator of this exchange-section, of the second part of the call-number of the called subscriber, i. e., the "number-signal", comprising the ten and unit numerals of that call-number. 110

When this number-signal is received at the terminator of the exchange-section of the called subscriber, the apparatus at once causes a busy-test to be made, to ascertain whether the called subscriber is busy or not. Should this called subscriber be busy, a special "busy" signal is sent back to the calling subscriber, notifying him that the party, he wishes to talk to, is at present 115 busy, and immediately thereafter, all the connection so far completed, is disestablished, and all parts used in that connection, return to normal position. 120

If, however, the line of the called subscriber is not busy, then the terminator immediately places the terminator-shuttle, now forming the end of the line leading from the calling subscriber to the exchange section of the called subscriber, into connection with the line-terminals of the called 130

subscriber. The ringing mechanism is put into operation, and calls the called subscriber at intervals during a predetermined period of time, until he takes his receiver off the hook. This act automatically cuts out the ringing mechanism and places the talking battery into the circuit, enabling the two subscribers to hold conversation. In this circuit, so established, there are supervisory magnets, depending for their energization upon the current flowing over the line. As long as these magnets are energized, connection between the two subscribers is maintained. When, however, one of the subscribers hangs up his receiver, the circuit is opened, the supervisory magnets become deenergized, and various mechanisms at both exchange-sections, the one of the calling subscriber as well as the one of the called subscriber, at once proceed to dis-establish connection between the two subscribers and cause all parts to return to normal position.

The present invention is illustrated in one form of construction in the accompanying drawings, forming part of this application, in which: Fig. 1 is a diagrammatical view of the subscriber's sender; Fig. 2 is a diagrammatical view of the ten-selector of the allotter; Fig. 3 is a similar view of the unit-selector; Fig. 4 a similar view of the originator of an exchange section; Fig. 5 a similar view of the pilot; Fig. 6 a similar view of the terminator.

For the better reading of these drawings, Figs. 1, 4 and 3 should be arranged from the left to the right in one row, and Fig. 6 under Fig. 1, Fig. 5 under Fig. 4, and Fig. 2 under Fig. 3.

Fig. 7 is a detailed diagram of the circuit for the group-signal; Fig. 8 the circuit for the individual line-relay; Fig. 9 the circuit for the thousands-numeral translator; Fig. 10 indicates the circuit for rendering the hundred-selector operative; Fig. 11 indicates the hundred-numeral translator circuit and the pilot-clutch circuit; Fig. 12 is the circuit over which the subscriber's sender is restarted; Fig. 13 is the number-signal circuit; Fig. 14 is the tens-numeral translator circuit; Fig. 15 the units-numeral translator circuit; Fig. 16 illustrates the terminator busy-test circuit and the terminator clutch-magnet circuit; Fig. 17 illustrates the talking circuit; Fig. 18 illustrates the pilot busy-test circuit; Fig. 19 illustrates the ringing-back circuit when the pilot is busy; Fig. 20 illustrates a similar circuit when the terminator is busy; Fig. 21 illustrates the circuits for ringing-forward and back; Fig. 22 illustrates the group-signal selector resetting-circuit; Fig. 23 illustrates the number-signal selector resetting-circuit; Fig. 24 illustrates the circuit for clearing-out the terminator-shuttle; Fig. 25 illustrates the circuit for

clearing-out the pilot- and originator-shuttle; Fig. 26 illustrates the circuit for selecting the pilot-shuttle; Fig. 27 a similar circuit for selecting the terminator-shuttle; Figs. 28 and 29 illustrate diagrammatically the scheme of trunking between sections or exchanges; Fig. 30 is a front view of one of the shuttle-lifting devices, used in the originator and also in the terminator of an exchange-section; Fig. 31 is an end-elevation of the same device; Fig. 32 is a vertical cross-section in the line A—B of Fig. 30; Fig. 33 is a longitudinal section through the friction-clutch of the allotter; Figs. 34 and 35 are perspective side-views of the shuttle-lifter; Figs. 36, 37, 38 are side-elevations of the shuttles in different phases of their operation; Fig. 39 is a perspective side-view of the line-terminals and the shuttle contact-brushes; Fig. 40 is a perspective side-view of the originator-shuttle selector; Fig. 41 is a front-elevation of the terminator-shuttle selector; Fig. 42 is a detail of the same, also used in the pilot-shuttle selector; Fig. 43 is a vertical cross-section in the line C—D of Fig. 41; Figs. 44 and 45 are detail-views of Fig. 41; Fig. 46 is a perspective view of the mechanical arrangement for ringing and clearing-out; Fig. 47 a longitudinal cross-section of a detail of same; Fig. 48 is a perspective view of the ring-back device; Fig. 49 is a front-elevation, Fig. 50 a plan view, and Fig. 51 an end-elevation of a signal-receiving mechanism; Fig. 52 is a cross-section in the line E—F of Fig. 49, looking to the left; Fig. 53 a similar view, looking to the right; Fig. 54 a detail of Fig. 49, and Figures 55 and 56 represent perspective views respectively of the upper and lower halves of the assembled mechanism comprising the complete machine.

The signal-sending apparatus, illustrated in Fig. 1 of the drawings, forms the subject matter, as stated before, of the U. S. Patent to Ernest A. Faller, No. 757,030, of April 12, 1904, and its construction will not be claimed in the present application. It consists of a series of number-rings, 1, 2, 3, 4, spread out in the drawings so as to be more clearly seen, the thousand number-ring at the bottom, with the hundred, ten and unit number-rings in sequence above. Each number-ring is provided with a contact spring 9, 11, 12, 13, and has on its periphery a series of indentations and, diametrically opposite thereto, a series of numerals, letters, or other characters, capable of indicating the call-numbers of the subscribers connected to the exchange.

Adapted to rest in the indentations on the number-rings are a series of contact-rollers 5, 6, 7, 8, capable of positioning the number-rings according to the numeral selected. A series of make-and-break wheels 19, 120, 176 and 178 are located within the number-rings

on a common shaft. These wheels are provided with a series of teeth and, opposite thereto, an upturned controlling-rim 14, 15, 16 and 17. The make-and-break wheel of 5 the thousand number-ring 1 has an additional or eleventh tooth 20. The make-and-break wheels are arranged in pairs, so that during the first half of the revolutions of the make-and-break wheels, the teeth of the 10 thousand and hundred make-and-break wheels are connected through stationary contact-springs 18 and 121, to the lines A, B leading from the subscriber's sender to the exchange, and during the second half of the 15 revolution, the ten- and unit make-and-break wheels 176 and 178 through the springs 177 and 179, to the lines A, B. Secured to the shaft of the make-and-break wheels is a rotating commutator 84, having 20 a contact piece 85, which in its normal position bridges the contact springs 83, 83, and in its second position the contact springs 169, 169. The subscriber's sender is furthermore provided with a clockwork 31, and a 25 winding-knob 30, which clockwork, when wound up, is prevented from running down, by a lever forming the armature of the sender-magnet 32. The contact-lever 21 is 30 normally in contact with contact-springs 24 and 25, but when the winding-knob 30 is turned and released, this lever 21 is caused to make contact with the contact-springs 22 and 23. The subscriber's telephone set, 35 which is of any commercial form, is connected in multiple to the sender-terminals 87 and 233.

The mechanical devices used in the present invention are divided, as stated hereinbefore, into three sets of operating mechanism, 40 named respectively and in the manner of their use, the "originator," the "pilot" and the "terminator." Each of these devices is divided practically into a shuttle-selecting means and into a shuttle-lifting means. The shuttle-selecting means of the originator are 45 entirely mechanical, are illustrated in Fig. 40 and will more fully be described herein-after. The shuttle-selecting means of the pilot and of the terminator are mostly electrical and depend upon the shuttle, first selected in the originator and upon the trunk-line, selected in the pilot for making connection between the pilot and the terminator, 50 all of which will hereinafter be more fully described.

The devices for lifting the shuttles are 55 substantially identical in construction for the three sets of operating mechanism, provided in each exchange-section, and their principal operation consists in so controlling the lifting of a shuttle, as to cause it to stop at and make contact with a predetermined line- or trunk-line-terminal and form part of the complete connection between a calling 60 and a called subscriber. The height to which

a shuttle is to be lifted for the purpose of making contact with a certain line-terminal, depends upon the relative position of certain mechanical parts, which position is practically controlled by the group-signal and 70 number-signal of each subscriber. The devices for determining the height to which a shuttle is to be lifted in the different sets of operating mechanism are called "translators," and they consist, in a general way, 75 of two horizontal ratchet-cylinders 264 and 265, Fig. 30, which are normally frictionally driven from a suitable power device by means of the shaft 266 and the gear 267 in mesh with a second gear 268, Fig. 33, forming 80 the loose member of a friction-clutch, the fast members of which are 269 and 270. Each of the ratchet-cylinders 264 and 265 has a series of helically arranged teeth or stops 271, each of the teeth 271 adapted to 85 be engaged by a pawl 272, Fig. 32, preferably arranged on a common shaft 273. There are as many pawls to each ratchet-cylinder as there are helically arranged teeth. Each of the pawls is controlled by a 90 spring 274, so as to force it against the ratchet-cylinder, but normally prevented from falling into the path of its tooth by a detent 275, which engages a pin 276 of the pawl. The detents 275 form the armatures 95 of a series of magnets 277, and when one of the magnets 277 becomes energized, it attracts its armature 275 against the force of a spring 278, and releases the pawl 272, which, by falling into the path of a tooth 271 100 of one of the ratchet-cylinders 264, 265, stops the rotation of the same. It is obvious that, according to the ten teeth or stops provided on each ratchet-cylinder, 105 there are ten positions, at any one of which the ratchet-cylinders may stop.

Each of the horizontal ratchet-cylinders 264, 265 drives a vertical cylinder 279 and 110 280 by means of mitre-gears. The two cylinders 279 and 280 are each arranged on the outer end of the ratchet-cylinders 264 and 265, and each is also provided with a series of helically arranged stops. The vertical cylinder 279, which is driven from the ratchet-cylinder 264, is provided with ten 115 stops or teeth 281, of considerable length and forming one complete turn of a helix around the cylinder 279. The cylinder 280 driven by the ratchet-cylinder 265, however, is provided with one hundred stops or teeth 120 282 arranged in a helix of ten complete turns. The rise of each turn of the cylinder 280 corresponds to the length of a tooth 281 of the cylinder 279 or, in other words, the pitch of the helix of the cylinder 279 is 125 ten times the pitch of the helix of the cylinder 280. A horizontal shaft 283 located at the upper end of the shuttle-lifting mechanism, carries a loose pulley connected to one member of a clutch 304, which pulley 130

is driven by means of a belt 284 from an extraneous source of power and is connected by means of a belt 285 to a lower horizontal shaft 326, Fig. 40. The shafts 283 and 286 are provided with sprocket-gears 287 and 288, Fig. 31, carrying driving chains 289 and 290, to which are secured two working-beams 291 and 292, by means of cross-heads 299 and 300. Each of the working-beams 291 and 292, Figs. 34 and 35, is provided with a lever-shaft 293, carrying on that side on which the vertical cylinder 279 is located, the lever arm 294 with a roller 295, capable of being moved outward by that tooth of the vertical cylinder 279 which is placed in its path when the normally rotating vertical cylinder 279 is caused to stop by the stopping of the horizontal ratchet-cylinder 264, Figs. 36, 37 and 38. The opposite end of the lever-shaft 293 is provided with a lever-arm 296, capable of pushing forward a dog 297, which, thereby, is placed in line with a tooth 282 of the vertical cylinder 280, when that cylinder 280 is caused to stop by the stopping of the horizontal ratchet-cylinder 265.

The working-beams 291 and 292 are furthermore provided with shuttle-lifting plates 298, pivoted at both ends to the cross-heads 299 and 300, secured to the driving chains 289 and 290 and carrying the lever-shaft 293. The lifting-plates are capable of being dipped by their own weight when the stop 301, located on one of the lifting-plates, is released by the detent 302 pivoted to a short shaft 303 carrying a second lever 304. This last lever 304 is capable of being lifted by the rear-end of the dog 297, which was pushed forward in line with a tooth 282 of the vertical cylinder 280, as hereinbefore stated.

The operation of the mechanical devices so far described is as follows: When one magnet 277 of each of the horizontal ratchet-cylinders 264, 265 has become energized, its armature 275 releases its pawl 272, which, in dropping into the path of one of the teeth 271, engages that tooth and stops each of the ratchet-cylinders 264, 265 in a predetermined position. The vertical cylinders 279 and 280 are thereby also stopped in a certain position, and the position of each of the vertical cylinders 279 and 280 corresponds to one of the digits 55 of the call-number of a subscriber. The long tooth 281 on the cylinder 279 in the originator and the terminator corresponds to the ten digit of the call-number of a subscriber, and the small tooth 282 on the cylinder 280 of the originator and the terminator, corresponds to the unit-digit of that call-number. The long tooth of the cylinder 279 in the pilot corresponds to the thousand-digit and the small tooth on the cylinder 280 in the pilot to the hundred-digit. By

the stopping of the ratchet-cylinders 264 and 265, the long tooth of the cylinder 279 and the small tooth of the cylinder 280 are now located in the path of the roller 295, on one end of the working-beams 291 and 292, and in the path of the dog 297 on the other end of the working-beams 291, 292. When now in the ascent of the working-beams 291, 292, the roller 295 glides unto the tooth 281 of the cylinder 279, Figs. 36 and 37, it is pressed outward and moves the lever 296 on the other side of the working-beams toward the cylinder 280. In the further upward movement of the working-beams 291, 292, the dog 297 of this lever 296 meets the tooth 282 of the cylinder 280, now placed in the path of this dog 297, which depresses this dog, and, thereby, lifts its rear end, which, acting against the lever 304, raises the detent 302 and allows the shuttle-lifting plate 298 to tilt or dip by its own weight, as clearly shown in Fig. 37.

The sprocket-wheel shafts 286 and 283 are normally at rest, and are connected by a friction-clutch 304', Figs. 4, 5, 6 and 30 to the common power device, as stated hereinbefore. When the clutch-mechanism 304', which in each of the three sets of mechanism, the originator, pilot and the terminator, is under the control of a magnet, is caused to operate, the sprocket-wheels 287 and 288 are revolved, and the chains 289 and 290 are caused to move in the direction of the arrow, Fig. 31, and lift one of the working-beams along the vertical cylinders 279, 280, the lifting-plate 298 of which takes along one of the shuttles, as hereinafter will be more fully described, and leaves that shuttle in a predetermined position and in contact with a predetermined line-terminal by the dropping or tilting of the shuttle-lifting plate 298 when its controlling mechanism makes contact with the teeth, respectively, of the vertical cylinders 279 and 280. The sprocket-wheel shafts 283 and 286 are disengaged from the power device when the working-beam has made a complete stroke, the shuttle-lifting plate 298 having been restored to its normal position by its own weight when passing over the sprocket-wheels 287 secured to the upper shaft 283.

When the cross-head 300 during the stroke of the working-beam 291 passes the lower sprocket-wheel 288, it engages the lever 333, provided with a connecting-rod 334, having an elongated slot at its end, which surrounds a pin of a lever 335, secured to the shaft 273, on which the pawls 272 are loosely mounted, and rocks the shaft 273. Each of the pawls 272 is provided with an elongated diametrical slot 336, containing a pin 337 passing through the shaft 273 in such a way that the pawls 272 are capable of falling forward into the path of a tooth 271 of the ratchet-cylinder 130

265, and when the lever 333 and the connecting-rod 334 are operated, all the pawls now in contact with the ratchet-cylinder are forced back through those pins into normal position, wherein they are held by the detents 275 engaging the pins 276 of the pawls 272, as shown in dotted lines in Fig. 32.

The traveling terminals or shuttles employed in the present invention are, as stated before, the equivalents of the plugs provided in a manual exchange. There are twelve shuttles in each of the sets of operating mechanism, the originator, the pilot and the terminator, forming the ends, respectively, of an equal number of link circuits.

It is one of the functions of the self-acting exchange to first provide an idle shuttle or link circuit for the calling subscriber in the originator of the machine, and then trace the link circuit of this shuttle to the pilot of the machine. At this part of the machine, the shuttle makes connection with the trunk-line desired by the calling subscriber and, thereby, extends the line already established, to a certain shuttle in the terminator, which, by being brought into contact with the line-terminal of the called subscriber, completes the connection between a calling and a called subscriber.

The shuttles in each of the sets of the operating mechanism are all identical in construction and are arranged to glide up and down between bars 305, so as to make contact with any of the line-terminals 82, 152 and 226, arranged on the terminal-boards 306, Fig. 31, opposite to and parallel with the plane of movement of the shuttles. Each shuttle comprises a casing 307, Figs. 36, 37, 38, having guiding flanges 308, embracing the bars 305 hereinbefore mentioned, so that the shuttle may glide up and down along the bars. Each shuttle is attached to an upper shuttle-ribbon, 89, 98 and 260, respectively, and a lower shuttle-ribbon 112, 115 and 245, respectively, which are secured to the spring-barrels of upper and lower ribbon-tensions 309 and 310. The springs of the lower ribbon-tensions 310 are considerably stronger than the springs of the upper ribbon-tensions 309, so that the tendency of the shuttles, when released, is always to return to their normal position at the lower ends of the bars 305.

The upper ribbon-tensions 309 are each provided with pawl- and ratchet-arrangements 311 for the purpose of holding the shuttles 81, 99 and 225 in the lifted position, the pawl 311 forming the armature of the resetting magnets 312, 313 and 314, so that when one of these magnets becomes energized and the pawl is removed from the ratchet of the upper ribbon-tension, the shuttle will be brought down under the

superior tension of the lower ribbon-tension 310. The contact-lever 315 of each shuttle is illustrated in Fig. 39, which also shows the manner of making contact with the line-terminals 82, 152 and 226 respectively. Each subscriber is represented at the originator and at the terminator of his exchange-section by a set of line-terminals, consisting of three horizontally arranged conducting strips, Fig. 39. The upper one of the strips in the originator and terminator is connected to line A, leading to the subscriber's sender. The middle strip is connected to line B, and the lower strip in the originator and terminator is connected to the winding of the individual line-relay 42. The middle and the upper terminal-strip of the pilot are connected respectively to the trunk-lines A and B, leading from the pilot to the terminators of any exchange-section forming part of the entire system, some of these trunk-lines leading obviously also to the terminator of the exchange-section of which the pilot in question forms a part. The third strip in the pilot is connected respectively to protecting and selecting devices, as hereinafter will be more fully described.

The terminal-strips in the terminal-boards of the three sets of operating mechanism are identical in construction, and the terminal-strips in the originator are connected in multiple to the corresponding terminal-strips in the terminator. The terminal-strips in the pilot may be connected in multiple with the terminal-strips in the pilots of any other exchange-section forming the entire system. Each of the strips is provided with as many contact-points as there are link circuits or shuttles in each of the sets of operating mechanism in an exchange-section, in the present case, as stated herebefore, there are twelve such contact-points on each terminal-strip.

The shuttle action comprises, besides the contact lever or contact rocker 315, Figs. 36, 37, 38 and 39, the actuating lever 316, controlled by a spring 316', which tends to throw the lever upward in the position shown in Figs. 36 and 37. The actuating lever 316 is furthermore provided with a lifting-tooth 317 adapted to be engaged by the shuttle-lifting plate 298 of the working-beams 291 and 292. Pivoted to the lever 316 is a release lever 318 and secured to the lever 316 is a pin 319, the latter adapted to be engaged by a detent of the starting lever 320. The starting lever 320 is of the form of a bell-crank, the horizontal arm of which ends in the detent mentioned, and the vertical arm of which is provided with a recess and is adapted to be engaged by one of the dogs 321, as hereinafter will be more fully described.

The normal position of the shuttle action is illustrated in Fig. 38, the contact lever

315 and the release lever 318 being shown in solid lines in the position they occupy when the connection is established and in dotted lines the position they occupy after the 5 shuttle has begun its movement to normal during disconnection. All the shuttles are normally located in the lowest position at the ends of the bars 305, with the exception of one shuttle in the originator, which is always 10 ready to be lifted. This shuttle is in the condition illustrated in Fig. 36, the vertical arm of the starting lever 320 has been pushed in, its detent has released the pin 319 of the actuating lever 316, which, under the 15 action of its spring has been forced outward, and its lifting-tooth 317 is placed in the path of the shuttle-lifting plate 298 of the working-beams 291, 292.

When now one of the clutch-magnets 79, 20 150, 220 becomes energized, and operates the friction-clutch 304' so as to impart motion from the power device to the sprockets 287, 288, and to the shuttle-lifting plate 298, which normally is below the normal position 25 of the shuttles, the plate engages in its ascent the lifting-tooth 317 of the protruding actuating lever 316 of that shuttle which is ready to be lifted, and lifts this shuttle to the position and in contact with the desired 30 line-terminal, as already described.

When this position is reached, the shuttle-lifting plate 298 is tilted by the operation of the devices hereinbefore stated, and in the further upward movement of the working-beams 291, 292, one of the fingers 323, Fig. 38, of the working-beams presses against the lower end of the actuating lever 316 and forces the same inward, where it is again reached by the detent of the starting lever 320, engaging the pin 319 of the actuating lever 316. The release lever 318 having 40 engaged the pin 324 on the contact lever 315 forces the same forward into contact with a set of the line-terminals, and 45 the release lever 318 engages a tooth of the rack 325, corresponding to the selected position.

After the termination of the connection between two talking subscribers, and on the 50 energization of the resetting magnets 312, 313 and 314, the tension of the lower ribbon-tension causes the shuttle to return to its normal position. In doing so, the release lever 318 is lifted by passing the tooth of the rack 325 on which it was resting, this lever thereby is disengaged from the pin 324 of the contact lever 315, and this contact lever under the tension of its spring leaves the terminal-contacts, as shown in dotted 55 lines in Fig. 38, and all parts of the shuttle action are again in normal position.

In the present self-acting exchange it is imperative, of course, as there are no movable parts individual to the subscribers, except 60 the armatures of the individual line

relays, that selecting devices must be provided to place the operating mechanism including the power device at the disposal of a calling subscriber, for the purpose of selecting a link circuit connected to the 70 shuttles, and isolating it from the rest of the devices as long as connection between a calling and a called subscriber is maintained.

In order, therefore, to bring about an uninterrupted operation of the exchange so 75 that any calling subscriber within the number limited by the percentage basis or within the number of link circuits, may be able to send a call through the exchange resulting in connection with a called subscriber, it is 80 necessary that there should be always one shuttle at the originator in condition ready to be lifted into connection with the line-terminals of a calling subscriber.

This is accomplished by the device illustrated most clearly in Fig. 40, which consists of a shaft 326, to which is secured a series of cam-disks 327. The pulley 328 on the shaft 326, is driven from the common source of power by means of a belt 285 (see 90 Figure 30). The pulley 328 forms the loose member of a friction-clutch, the fast member 329 of which is secured to the shaft 326, so that normally the pulley 328 is rotating, but the shaft 326 is at rest, because one of the pairs of disks 327 is held by engaging a pin 330 of a dog 321. The disks 327 are arranged in pairs. Each disk is provided with a tooth 331, and the teeth of each pair of disks being in one line, the pairs of teeth 100 are arranged in a helix around the shaft 326. There are as many pairs of disks as there are shuttles or link circuits. Parallel to the shaft 326 is located a frame carrying a series of dogs 321, of the same number as there are pairs of disks 327, or as there are 105 shuttles. Each dog 321 is capable of being moved forward by the teeth 331 of the disks 327 into engagement with the recess of the starting lever 320 of the shuttle action of an 110 originator-shuttle, and each dog 321 is provided with a pin 330, protruding on both sides of the dog, and is controlled by a spiral spring 332, which returns the dog to its 115 normal position when disengaged from the teeth 331. The dog moves very loosely in its seat in the frame so that it may also make a slight upward movement.

The pairs of teeth 331 are helically arranged, as heretofore stated, and capable of engaging the pin 330 of the dog 321, but only one dog can be engaged at one time and forced forward, and, therefore, when engaging a starting lever 320, only one shuttle can be so operated as to release its actuating lever 316 and place the lifting-tooth 317 of the same into the path of the shuttle-lifting plate 298 of the working-beams 291, 292. It will be seen that the 125 selection of an idle shuttle or an unemployed 130

link circuit in the originator is an entirely mechanical one.

When one shuttle at the originator is being lifted, the pins of the dog which tripped the starting lever of this shuttle being removed from the teeth of its cam-disks, the shaft 326 will resume its rotation, another pair of cam-disks will engage another dog, provided the same has been depressed by a shuttle, and the shaft 326 will again be brought to rest. Should any of the other adjoining shuttles be busy, the shaft 326 will continue to rotate until a pair of cam-disks 327 does meet a dog depressed by a shuttle, and then come to rest. It will be seen, therefore, that only one shuttle is capable of being lifted at one time. The frictional torque of the disks 327 is sufficient to overcome the tension of the spring 332 (see Figure 40). These springs being at an angle tend to pull the part 321 both backwards and upwards. The downward pull of the shuttle which is transmitted to the dog through the lever 320 overcomes the upward tension of the dog and keeps it down. As soon as the shuttle is lifted by the lifting mechanism the hook 320 exerts an upward pull upon the dog 321 sufficient to free its pin 330 from engagement with the nose 331 of the cam disk 327. As soon as this pin is clear of the tooth 331 the spring 332 pulls the dog back to its extreme position. It will be seen in Fig. 38, which shows a section through the shuttle, that the lever 320 is of such a shape that the upper edge of the notch in said lever projects outwardly a far greater distance than the lower edge. Consequently, (see Fig. 40) the shuttle lever 320 in its descent allows the retracted dog 321 to pass the said lever 320 until the projecting upper edge strikes the said dog and depresses it.

Having stated heretofore, that the traveling terminals or shuttles form the equivalents of the plugs in a manual exchange, it will now become necessary in the further operation of the device, to trace the link-circuit selected at the originator, to the pilot and bring the shuttle at the pilot which forms the other end of that link circuit, the first end of which was selected as just described, into position to be lifted by the shuttle-lifting plate of the pilot, which operation will be more fully described after the description of the normal operation of the machine.

As heretofore stated, the operation of the shuttle-lifting mechanism on all three sets of operating mechanism may be considered to be controlled by the group-signal and the number-signal forming the call-number of a subscriber connected to the exchange. The controlling of the shuttle-lifting mechanism at the originator of the exchange is brought about by a device called the "allotter." This allotter comprises, among other parts a commutator, a traveling brush, the ratchet cyl-

inders 264, 265, pawls 272, controlling the ratchet cylinders, armatures 275, magnets 277 controlling the pawls, and a power device 268 for imparting motion to said allotter. Under normal conditions and when no calls are in process of being made the traveling brush as well as the ratchet cylinders 264, 265 are constantly in motion. It is the purpose of the allotter to cause any one of the idle shutters in the originator to be placed in connection with the terminal clip of that calling subscriber who caused its operation in the first place, and this is accomplished through the medium of the ratchet cylinders 264, 265 in connection with the vertical cylinders 279, 280, and the mechanism provided on the working beam.

The allotter is illustrated most clearly in Figs. 2 and 3 of the drawings and comprises the isolator, the ten-selector and the unit-selector, and its object is to so position the vertical cylinders 279 and 280 of the originator as to lift the originator-shuttle into contact with the line-terminals of the calling subscriber. The isolator, illustrated at the bottom of Fig. 2, consists of a series of terminal-clips 44, one for each line connected to the exchange-section. The terminal-clips are arranged in groups of ten, each group having an eleventh clip 46 connected to battery and ground. The isolator comprises further on a suitable frame, an isolator-bar 338 slidably supported by pins or bolts 339 and provided with a series of isolator-blades 340, secured to the bar 338 and insulated therefrom, which blades 340 are capable of normally bridging all eleven clips, forming one group.

The isolator-bar 338 is capable of lateral movement by means of a bell-crank lever 67 held under tension of a spring 341 by a detent 66, which latter forms the armature of the isolator-magnet 64. Each of the isolator-clips 44 is connected to one of the contact-points 59 on the ten-selector of the device. The contact-points 59 belonging to one and the same group of clips, are arranged in radial lines around the axis of the trailer-arm 58. Each group of contact-points 59 is provided with a ten-selector magnet 47, connected on one side to the eleventh or ground-clip 46 of the isolator, and on the other side to a battery-ring 48, which, in turn, leads through battery to ground.

Each of the ten-selector magnets 47 is provided with an armature 60, acting as a detent for a stop 61, the latter capable of dropping into the path of the normally rotating trailer-arm 58, so that this trailer-arm, which is frictionally secured to its shaft, may stop on that row of contact-points 59, belonging to the energized ten-selector magnet 47.

The trailer-arm 58 consists of two series of contact-brushes, an outer series 68 capable

of making contact with the contact-points 59, and an inner series 69, arranged to slide upon a series of rings 70, each of the rings connected to a stop-magnet 71 of the unit-selector, Fig. 3, as hereinafter will be more fully described.

The outer series and the inner series of contact-brushes of the trailer-arm 58 are connected in pairs, respectively, the outermost brush of the outer series to the innermost brush of the inner series, etc., etc.

Each of the stops 61 is capable of making contact with contact-points 62, the stops 61 being connected to the contact-ring 48, to which also the magnets 47 are connected, and the contact-points 62 are connected to the outer ring 63 and through the isolator-magnet 64 to ground 65.

The construction of the unit-selector, Fig. 3 of the drawings, is very similar to that of the ten-selector. The unit-selector consists of a series of magnets 71, each of which is connected to one of the rings 70 of the ten-selector, Fig. 2, and through a battery-ring 72 to battery and ground. Each of the magnets 71 is provided with an armature 342 acting as a detent for the stops 343, which latter are capable of dropping into the path of the normally rotating trailer-arm 73 of the unit-selector. The trailer-arm 73 is frictionally secured to its constantly rotating shaft and is provided with two contact-brushes 77, 78. The inner contact-brush 77 glides on a ring 76 connected to ground 75. The outer contact-brush 78 is capable of making contact in succession with contact-points 74, all of which are connected together, and through the clutch-magnet 79, Fig. 4, to battery and ground. The shafts of both trailer-arms are driven by a common power device.

The parts of the allotter, so far described, are used for controlling the shuttle-lifting device of the originator. In order to accomplish this, the trailer-arms 58 and 73 may be considered to be connected by means of mitre-gears with the vertical cylinders 279, 280, and by the stopping of the trailer-arms, the teeth of these vertical cylinders will be so located as to place the long tooth on the ten-translator side and the short tooth on the unit-translator side, into the path of the roller 295 and the dog 297, respectively, of the working-beams 291, 292.

The release of the trailer-arms 58 and 73, when the same have been stopped by the energization of one magnet each at the ten-selector and unit-selector, is brought about by the connecting-rod 334 acting tangentially on the rotatable rings 72 and 63, which are provided with fingers 344 and 345 acting against short lever-arms 346 and 347 on the stops 61 and 343. The fingers 344 and 345 force the stops 61 and 343, respectively, into engagement with the detents 60 and

342, releasing thereby the trailer-arms 58 and 73, which then may resume their normal rotation.

The control of the shuttle-lifting mechanism at the pilot and the terminator of an exchange-section is brought about by the signal-receiving devices called thousand-, hundred-, ten and unit-selectors. As stated heretofore, the thousand- and hundred-selectors receive their part of the group-signal simultaneously, and the ten- and unit-selectors in the same way.

All the selectors in the present self-acting exchange are substantially identical in construction and are of that type in which a trailer-arm, having performed its step-by-step selecting act, returns to the zero position, by completing one full revolution, but not by reversing its direction of rotation, as in some other selectors.

The selectors, illustrated in Figs. 49 to 54, are arranged in pairs and connected to a normally rotating shaft 348, carrying a gear 349, to which motion is imparted by the extraneous power device of the exchange. The frictional connection between the constantly rotating driving shaft and the intermittently rotating driven shaft is clearly shown in Fig. 54. The driven shaft 350 carries part of a friction-clutch 351, furthermore the insulating bushing 352, the make-and-break wheel 353, the hub of which acts as a contact-ring, and a second contact-ring 354, also an escapement-wheel 355 and, insulated therefrom, the trailer-arm 356.

Secured to the frame of the selector is an insulated disk 357, having twelve contact-points 358, ten of which correspond to the numerals "0" to "9," one for the zero position and an idle contact-point. The escapement-wheel 355 is engaged by an escapement-lever 359, carrying the armature 360 of the selector-magnet and normally holding the escapement-wheel 355 at rest. For each impulse sent through the selector-magnet, the driving-shaft 348 will allow the driven shaft 350 to rotate the distance of one tooth on the escapement-wheel 355, and the escapement-arm 356 will move from one contact-point 358 to another. The selector-magnet is connected on one side to the contact-spring 361 capable of making contact with the make-and-break wheel 353, the other side of the magnet is connected to battery and ground at the exchange. The trailer-arms 356 of the thousand- and ten-selector are wired to the contact-ring 354 and through the contact-spring 362 to ground; the trailer-arms of the hundred- and unit-selector to battery and ground. The selector-magnets are understood to be the selector-magnets illustrated in Figs. 5 and 6 and indicated with the numbers 104, 119, 161, and 181, and the trailer-arms, respectively, with the numbers 139, 126, 174 and 189. 130

- switch 172, Fig. 6, operated by the ten-selector is illustrated in Figs. 51 and 52, in which the same is shown by three vertical springs, the middle one of which is capable of being 50 acted upon by the insulated lever 175 already shown in Fig. 6. The contact-points 358 are, of course, identical, respectively, with the contact-points 130, 138, on Fig. 5 and 184, 190 on Fig. 6.
- 10 It is to be understood that the cut-over switch 172 is present only at the ten-selector located at the terminator of an exchange-section and is not present at the thousand-, hundred- and unit-selectors. The reason for 15 this is that, as stated in the preamble of this specification, it is most desirable to send the impulses for starting a sender, and the selective impulses over different circuits. The selective impulses are sent over the lines, respectively, and the common ground, whereas the impulse for re-starting the sender-magnet 32 should be sent over an entirely metallic circuit. The number-signal will not be received at the terminator should all shuttles at the terminator be busy, and, therefore, a device is provided for the purpose of making connection between the sender and the selectors, which device is subject to 25 the existence of at least one idle shuttle.
- 30 If there is an idle shuttle in the terminator, a path is provided through a cut-in commutator, as will clearly appear from the description of the general operation of the exchange. This impulse passes over this 35 cut-in commutator through the sender-magnet and also the ten-selector magnet, causing the ten-selector trailer-arm to move one step, remove the detent 175 from the movable spring of the cut-over switch 172, and 40 allow the same to make contact with the other stationary spring of the cut-over switch, thereby closing an entirely metallic circuit.
- 45 *Operation of the self-acting telephone exchange.*
- The entire operation of the apparatus may be divided into the operation at the subscribers' station and the operation at the 50 self-acting exchange.
- The first act of the subscriber consists in combining the numerals of the number rings 1, 2, 3, 4 of the subscriber's sender, Fig. 1, to the figure forming the characteristic or 55 call number of the called subscriber. This act constitutes properly the pre-establishing of a signal as clearly set forth in the U. S. patent to Faller No. 757,030. It consists in turning at will, each of the number rings 60 1, 2, 3, 4, until the desired combination of numerals is shown in its proper place. The rollers 5, 6, 7, 8, of the signal sender, enter into the indentations corresponding to the selected numerals on the number rings 1, 2, 3, 4, and the contact springs 9, 11, 12, 13 of the number rings, thereby, are so located as at times to make contact of a predetermined duration with the rims 14, 15, 16, 17 constituting controlling contacts of the make-and-break devices. 70
- The stationary spring 18 of the thousand make-and-break device is normally in contact with an eleventh tooth 20 of the make-and-break wheel. The contact lever 21 is normally disconnected from the contact springs 22, 23. One contact spring of this pair of springs is connected over the ground terminal 26 and wire joint 27 of the sender to the ground 29. 75
- The second operation in sending a call 80 from the subscriber's station to the exchange for the purpose of making connection with a called subscriber consists in turning the knob 30 to its limit and then releasing it, which results in winding up the clock work 85 31 of the sender, but the same cannot run off until the sender magnet 32 has become energized. By releasing the knob 30, the contact lever 21 makes contact with the contact springs 22, 23, and ground 29 is hereby 90 connected to the subscriber's sender.
- This act of the subscriber results in sending an electrical impulse over the following circuit:— 95
- From ground 29 at the subscriber's sender to wire joint 27, the ground terminal 26, the contact spring 22, the contact lever 21, wire joints 33, 34, 35, the roller 5 in contact with the thousand number ring 1, the contact spring 9 of the thousand number ring 1, the controlling rim 14, of the thousand make-and-break device 19, the eleventh tooth 20 thereof, the stationary contact spring 18, wire joints 36, 37, 38, to the line-terminal 39 of the sender, over line A 100 and wire joint 40 to the originator of the exchange section of the self-acting exchange to which the calling subscriber is connected, through the armature 41, Fig. 4, of the individual line relay 42 of the calling subscriber, the armature contact 43, to the allotter and the individual terminal clip 44, Fig. 2 of the isolator thereof, the isolator blade 45 to the ground-clip 46 of the same row 105 of terminal clips of the isolator, to the stop magnet 47 of the group, the battery ring 48 of the group selector of the allotter, and over wire joints 49, Fig. 3, 50, 51, 52, 53, 54 to the battery 55, wire joint 56 and ground 57 at the exchange, Fig. 4. 110
- The impulse set over this circuit causes the energization of the magnet 47 and the stopping of the trailer arm 58 of the group selector of the allotter on the row of contact points 59 corresponding to the group of ten subscribers' stations to which the calling subscriber belongs. When the armature 60 of the stop magnet 47 is attracted and releases the stop 61, a circuit is closed through the back contact 62 of this stop as follows:— 115
- 120
- 125
- 130

From ground 57, wire joint 56 to battery 55 at the exchange, Fig. 4, wire joints 54, 53, 52, 51, 50, 49, Fig. 3, to the inner battery ring 48 Fig. 2, of the group selector 5 of the allotter, to the stop 61, its back contact 62, the outer ring 63 of the group selector, to the isolator magnet 64 and to ground 65, Fig. 2. The current passing over this circuit effects the energization of the isolator magnet 64 whereby the armature 66 of the same is attracted, the isolator lever 67 released and the isolator blades 45 removed from the terminal clips 44, 46. The connection between any of the terminals of this group of ten terminals and the ground terminal clip 46 has now been severed and no other stop magnet of the group selector can be energized until the isolator blades 45 are again restored.

20 As there is still ground retained at the sender, a further circuit is now being closed by the trailer arm 58 stopping on one of the rows of contact points 59, as follows:—

25 From ground 29 at the subscriber's sender over line A to the self-acting exchange as heretofore described, the individual terminal clip 44 of the calling subscriber hereinbefore mentioned, the innermost contact point of the rows of contact points 59 30 of the group selector of the allotter corresponding to and connected with the terminal clip 44, the brush of the outer series of brushes 68 of the trailer arm 58 now resting thereon, the brush of the inner 35 series of brushes 69 connected to that brush of the outer series, the contact ring 70 of the series of contact rings upon which this brush is now resting, the stop magnet 71, Fig. 3, of the unit selector of the allotter 40 connected to this ring 70, the outer battery ring 72 of the unit selector, to wire joints 49, 50, 51, 52, 53, 54, to battery 55 wire joint 56, to ground 57 at the exchange, as indicated by the heavy line in Figs. 1 to 4 of the 45 drawings.

The effect of current passing over this circuit is to energize the stop magnet 71 of the unit selector, and to stop the trailer arm 73 of the unit selector on one of the 50 contact points 74 corresponding to the unit numeral of the characteristic number of the calling subscriber.

55 The stopping of the trailer arm 73 of the unit selector of the allotter closes the following circuit:—

From ground 75, Fig. 3, at the exchange, to the inner contact ring 76 of the unit selector now resting thereon, the outer brush 78 of the trailer arm connected therewith, 60 the contact point of the series of connected contact points 74 of the unit selector upon which this outer brush 78 is now resting, to the clutch magnet 79 of the originator, Fig. 4, to wire joints 50, 51, 52, 53, 54, through 65 battery 55, wire joint 56 to ground 57.

The effect of current passing over this circuit is to energize the clutch magnet 79, Fig. 4, and to release the shuttle lifting mechanism 80 of the originator.

The selection of one of the shuttles 81, 79 of which there are twelve, and the devices for lifting the selected shuttle into contact with the line terminals 82 of the calling subscriber have already been fully described.

When the selected shuttle 81 has made 75 contact with the line terminals 82 of the calling subscriber, a circuit is established as follows:—

From ground 29 at the calling subscriber's sender, Fig. 1, wire joint 27, to the ground 80 terminal 26, the contact spring 22, contact-lever 21, the contact spring 23, to the contact spring 83 of the commutator 84, now bridged by the contact piece 85 of the rotating part of the commutator, wire joint 86, 85 through the sender magnet 32, to the sender terminal 87 of the line B, over line B wire joint 88 to the originator of the self-acting exchange, Fig. 4, to the upper line terminal 82 of the line B at the originator, to the 90 upper contact brush 125 of the shuttle 81 now in contact therewith, the upper shuttle ribbon 89 carrying the shuttle 81, the contact spring 90, wire joint 91, contact 92, armature 93 of the clearing-out control relay 94, wire joint 95, the upper set of the ring-back contacts 96, Fig. 5, to the upper contact spring 97 of the pilot, the upper shuttle ribbon 98 of the pilot shuttle 99, the upper contact-brush 101 of the pilot- 100 shuttle 99 which shuttle is still in its position of rest and in contact with contact spring 102, the wire joint 103, through the magnet 104 of the hundred selector 100, wire joints 105, 106, 107, 108, 109, Fig. 5, and 51, 105 52, 53, 54, to battery 55, wire joint 56, and ground 57 at the exchange, Fig. 4, also separately illustrated in Fig. 7. The lifting of the selected shuttle 81 in contact with the line terminal 82 of the calling subscriber, 110 closes another circuit over the lower terminal of the line terminal at the originator as follows:—

From ground 57, wire joint 56, battery 55, wire joints 54, 214, through the individual 115 line relay 42, wire joint 221, to the lower terminal of the line terminals 82 at the originator, contact brush 222 of the originator shuttle 81, to the ground 223. The effect of the current passing over this circuit is to 120 energize the relay 42 and attract the armatures 41 and 212, for the purpose of opening the circuit to the allotter, Figs. 2 and 3, reverting the same to common use of the calling subscribers, and closing a circuit to 125 be used for the busy test as hereinafter to be described. The circuit just described is shown in Fig. 8.

This circuit to the allotter is easily traced by following the heavy line starting at con- 130

tact 43 of relay 42 of Fig. 4, through Fig. 3, and Fig. 2 where the circuit terminates in the contact plate 44 of the one-hundred point switch.

5 The magnet 104 is not energized on account of its low resistance as compared with that of the sender magnet 32, and only the latter is energized and releases the clock-work 31 of the sender, as fully disclosed in 10 the U. S. Patent No. 757,030.

During the first half of the revolution of the make-and-break devices 19 of the subscriber's sender, the selecting impulses identifying the exchange section to which 15 the called subscriber is connected, are now sent into the exchange and, in particular, both sets of selecting impulses representing the thousand numeral and the hundred numeral of the call number of the called 20 subscriber, simultaneously.

The selecting impulses of the thousand numeral pass over the following circuit:—

From ground 29 at the subscriber's sender, Fig. 1, wire joint 27, to the ground terminal 26, the contact spring 22, the contact lever 21, wire joints 33, 34, 35, the roller 5, the thousand number ring 1, the contact spring 9 of the same, the rim 14 of the thousand make-and-break wheel 19, the teeth 30 of the make-and-break wheel, the stationary contact spring 18, making contact with the teeth, wire joints 36, 37, 38, to the sender terminal 39 of the line A, over line A, wire joints 40, 110, to the originator at the exchange, Fig. 4, the middle contact of the line terminal 82 at the originator, the middle brush 111 of the originator shuttle 81 now in contact therewith, the lower shuttle ribbon 112, the contact spring 113, the lower set 40 of ring-back contacts 96, Fig. 5, contact spring 114, the lower shuttle ribbon 115, the middle contact brush 116 of the pilot shuttle 99 which latter is still in its position of rest and in contact with the contact spring 45 117, wire joint 118, to the magnet 119 of the thousand selector 1000, wire joints 106, 107, 108, 109, Fig. 5, 51, 52, 53, 54, to battery 55, wire joint 56, to ground 57 at the exchange, Fig. 4 and Fig. 7.

50 The selecting impulses of the hundred numeral pass over the following circuit:—

From ground 29, Fig. 1, at the subscriber's sender, wire joint 27, to the ground terminal 26, the contact spring 22, the contact lever 21, wire joints 33, 34, 35, the roller 6, the hundred number ring 2, the contact spring 11 of the hundred number ring 2, the rim 15 of the hundred make-and-break wheel 120, the teeth of the make-and-break 60 wheel 120, the stationary contact spring 121 making contact with the teeth, wire joints 122, 123, 124, to the sender terminal 87 of line B, over line B, wire joint 88, to the originator at the exchange, Fig. 4, the upper 65 contact of the line terminal 82 at the origi-

nator, the upper contact brush 125 of the originator shuttle 81, now in contact therewith, the upper shuttle ribbon 89, the contact spring 90, wire joint 91, contact 92, armature 93 of the clearing-out control relay 70 94, wire joint 95, the upper set of the ring-back contacts 96, Fig. 5, the upper contact spring 97 of the pilot, the upper shuttle ribbon 98 of the pilot shuttle 99, the upper contact brush 101 of the pilot shuttle 99 75 which latter is still in its position of rest, the contact spring 102, wire joint 103, the magnet 104 of the hundred selector 100, wire joints 105, 106, 107, 108, 109, Fig. 5, 51, 52, 53, 54, to battery 55, wire joint 56, 80 and ground 57 at the exchange, Fig. 4 and Fig. 7.

The magnet 119 of the thousand selector as well as the magnet 104 of the hundred selector, respectively, receive the group signal, i. e., a number of impulses corresponding to the thousand and hundred numerals of the call number of the called subscriber, identifying that exchange section of the exchange system to which the called subscriber is 85 90 connected.

When the selector arm 126 of the thousand selector 1000 reaches its selective position, a circuit is established as follows:—

From ground 127 at the exchange, Fig. 5, 95 to wire joints 128, 129, the tip of the selector arm 126, the contact point 130 on which the tip is now resting, to one of the thousand translator magnets 131, wire joints 132, 107, 108, 109, Fig. 5, 51, 52, 53, 54, to battery 100 109, wire joint 56, and ground 57, Fig. 4 and Fig. 9.

The effect of this current is to energize one of the thousand translator magnets 131, which attracts its armature 132 and releases 105 its stop pawl 133 to engage a tooth of the ratchet 134 and stop the ratchet cylinder of the thousand translator in the position selected.

It is only in case of prolonged engagement 110 between arm 126 and one of the contacts 130, as when said arm stops on a selected contact, that a magnet 131 acts on its armature to thus release its stop pawl. This may be effected in a number of ways; for example, by making the magnets 131 relatively slow acting as by adjusting the normal distance of an armature 132 from its magnet, or by adjusting the tension of the armature spring, or both, so that the time that it takes the magnetism of one of said magnets to build up sufficiently to operate its armature will be longer than the time of contact between arm 126 and one of the contacts 130 120 when the said arm is passing over said contacts to its selected position. My invention, however, is not limited to any particular way of effecting the proper operation of these magnets.

As soon as the pawl 133 makes contact 130

with this tooth, another circuit is established from ground 127 at the exchange, Fig. 5, to wire joints 128, 135, trunk controlling relay 136, to wire joint 137, the contact point 138 of the hundred selector 100, on which the tip of the selector arm 139 of the hundred selector 100 is now resting, through this tip, to the pawl 133 of the thousand translator, the ratchet 134 of the thousand translator, wire joints 140, 132, 107, 108, 109, Fig. 5, and 51, 52, 53, 54, to battery 55, wire joint 56, and ground 57, Fig. 4 and Fig. 10.

The effect of this current is to energize the trunk controlling relay 136 which attracts its armature and closes the following circuit:—from ground 127, to wire joints 128, 135, the armature 141 of the relay 136, contact 142, upper contact blade of the contacts 143, contact 144, through the hundred translator magnet 145, wire joints 140, 132, 107, 108, 109, Fig. 5, and 51, 52, 53, 54, to battery 55, wire joint 56, and ground 57, Fig. 4 and Fig. 11.

The energization of the magnet 145 of the hundred translator results in the attraction of the armature 146 and the consequent dropping of the pawl 147 of the hundred translator into one of the teeth of the ratchet 148 of the hundred translator and stops the ratchet cylinder of the hundred translator in the position selected.

As soon as the pawl 147, Fig. 5, of the hundred translator makes contact with the tooth of the ratchet 148, a circuit is established as follows:

From ground 149 to the ratchet 148 of the hundred translator, the pawl 147 now in contact with the ratchet, the pilot clutch-magnet 150, wire joints 105, 106, 107, 108, 109, Fig. 5 and 51, 52, 53, 54, to battery 55, wire joint 56, and ground 57, Fig. 4 and Fig. 11. The energization of the clutch-magnet 150 results in the release of the shuttle lifting mechanism 151 of the pilot, causing one of the pilot shuttles 99 to make contact with the line terminals 152 of the trunkline leading to that exchange section to which the called subscriber is connected.

At this moment, complete connection is established between the sender of the calling subscriber and the terminator of that exchange station to which the called subscriber is connected. In the given example, the called subscriber is connected to the same exchange section as the calling subscriber, but it is obvious that the trunk-line which forms part of this connection, may lead to any other exchange section of the entire system to which the called subscriber may be connected.

It now becomes necessary to release the sender on its second half of the revolution of the make-and-break wheels, for the purpose of sending the number signal, i. e., that part of the entire signal to the exchange which

identifies the called subscriber at the exchange section to which he is connected.

When the pilot shuttle 99 has made contact with the line-terminals 152 of the trunkline leading to the exchange section of the called subscriber, a circuit is established as follows:—

From the upper end of the battery 55, at the exchange, Fig. 4 to wire joints 54, 53, 52, 51, Fig. 4, 109, Fig. 5, to wire joints 153, 154, 155, 156, 157, 158, 159, 160, Fig. 6, the magnet 161 of the ten selector 10, wire joint 162, the outer contact ring 163 of the selector cut-in 164, the contact point 165 on which the trailer arm 166 is now resting and by which it is connected to the ring 163, the upper group of the selector controller contacts 167, the right hand group of the ringing contacts 168, to the middle line-terminal 152, Fig. 5, of the trunkline on the pilot of the exchange section to which the calling subscriber is connected, the contact brush 116 of the pilot shuttle 99 now in contact therewith, the lower shuttle ribbon 115, the contact spring 114, the lower group of ring-back contacts 96, the contact spring 113, Fig. 4, of the originator, the lower shuttle ribbon 112 of the originator, the middle contact brush 111 of the originator shuttle 81, the middle line-terminal 82 forming the exchange terminal of the line A, wire joints 110, 40 over line A to the subscriber's sender, the sender terminal 39, Fig. 1, of the line A, wire joint 38, to contact springs 169, now bridged by contact piece 85 now in its second position, wire joint 83, through the sender magnet 32, wire joint 124, the sender terminal 87 of the line B, over line B, wire joint 88, Fig. 4, to the originator, the upper line terminal 82, the contact brush 125 of the originator shuttle 81 now in contact therewith, the upper shuttle ribbon 89, the contact 90, wire joint 91, contact 92, armature 93 of the clearing-out controlling relay 94, wire joint 95, the upper group of the ring-back contacts 96, Fig. 5, contact spring 97, the upper shuttle ribbon 98 of the pilot, the upper contact brush 101 of the pilot shuttle 99, the upper line terminal 152 of the trunk line leading to the exchange section of the called subscriber, the left hand group of the ringing contacts 168, the lower group of the selector controlling contacts 167, one of the inner contact points 170 of the selector cut-in 164, the inner contact ring 171 now connected with the trailer arm 166, the movable contact of the cut-over switch 172, the lower contact thereof, wire joint 173, Fig. 6, 56, Fig. 4, and the lower end of the battery 55.

It will be seen that this circuit is an entirely metallic one, differing from the circuits over which the selecting impulses are sent.

The establishment of this circuit results in the energization of the sender magnet 32, which releases the clockwork 31, and starts

- the make-and-break wheels of the sender on the second half of their revolution, simultaneously the magnet 161 of the ten selector 10 has received one impulse which causes the selector arm 174 to move one step and thereby remove the detent 175 from the cut-over switch 172 so that the movable contact spring of this switch is now in contact with the upper contact spring.
- 10 During the second half of the revolution of the make-and-break devices of the sender, the number signal, i. e., the selective impulses for the ten and unit selectors, identifying the called subscriber at his exchange section, and 15 both sets of impulses, for the ten and for the unit selector are again sent simultaneously.
- The selective impulses of the ten numerals of the entire signal pass over the following circuit:—
- 20 From the ground 29 at the subscriber's sender, wire joint 27 to the ground terminal 26, the contact spring 22, the contact lever 21, wire joints 33, 34, the roller 7 in contact with the ten number ring 3, the contact 25 spring 12 of the same, the controlling rim 16 of the ten make-and-break wheel 176, the teeth of the make-and-break wheel 176, the stationary contact spring 177, making contact therewith, wire joints 37, 38, the sender 30 terminal 39 of the line A, Fig. 1, over line A, wire joints 40, 110, Fig. 4, to the originator at the exchange, the middle line terminal 82 at the originator, the contact brush 111 of the originator shuttle 81 now in contact 35 therewith, the lower shuttle ribbon 112, the contact spring 113, the lower group of ring-back contacts 96, Fig. 5, the lower contact spring 114, the lower shuttle ribbon 115 of the pilot, the middle contact brush 116 of 40 the pilot shuttle 99, the middle terminal of the trunk-line terminals 152 leading to the exchange section of the called subscriber, the right hand group of ringing contacts 168, Fig. 6, at the exchange section of the called 45 subscriber, the upper group of selector controlling contacts 167, one of the outer contacts 165 of the selector cut-in 164 on which the trailer arm 166 is now resting, the outer contact-ring 163, wire joint 162, the magnet 161 of the ten selector of the exchange 50 section of the called subscriber, wire joints 160, 159, 158, 157, 156, 155, 154, 153, Fig. 6 and 109, Fig. 5, 51, 52, 53, 54, Fig. 4, to the battery 55, wire joint 56, and to ground 57, 55 see Fig. 13.
- The selecting impulses of the unit numeral of the entire signal pass over the following circuit:—
- From ground 29 at the subscriber's sender, 60 Fig. 1, to wire joint 27, to the ground terminal 26, the contact spring 22, the contact lever 21, wire joint 33, the roller 8 in contact with the unit number-ring 4, the contact-spring 13 of the same, the controlling rim 17 of the unit make-and-break wheel 65 178, the stationary contact spring 179, making contact therewith, wire joints 123, 124, the sender terminal 87, wire joint 240 of line B, Fig. 1, over line B, wire joint 88, to the originator at the exchange, the upper line-terminal 82 at the originator, the contact brush 125 of the originator shuttle 82 now in contact therewith, the upper shuttle ribbon 89, contact spring 90, wire joint 91, contact 92, armature 93 of the clearing-out controlling relay 94, wire joint 95, the upper group of the ring-back contacts 96, Fig. 5, the contact-spring 97, the upper shuttle ribbon 98, the upper contact brush 101 of the pilot shuttle 99, the upper line terminal 152 of the trunk-line leading to the exchange section of the called subscriber, over this trunk-line to the terminator of the exchange section of the called subscriber, Fig. 6, the left hand group of the ringing contacts 168, the lower group of the selector controlling contacts 167, the contact point of the inner row 170 of the selector cut-in 164, on which the trailer arm 166 is now resting, the inner contact ring 171, the movable contact spring of the cut-over switch 172, the upper contact spring of the same, wire joint 180, the magnet 181, of the unit selector, wire joints 160, 159, 158, 157, 156, 155, 154, 153, Fig. 6, 109, Fig. 5, 51, 52, 53, 54, to battery 55, wire joint 56 and ground 57, Fig. 4 also separately illustrated in Fig. 13.
- Each of the magnets, the magnet 161 of the ten selector and the magnet 181 of the unit selector now receive a number of impulses corresponding to the ten and unit numerals of the call number of the called subscriber.
- When the selector arm 174 of the ten selector has reached its selective position, a circuit is established as follows:—
- From ground 57, Fig. 4, 14, wire joint 56, the battery 55, wire joints 54, 53, 52, 51, Fig. 4, 109, Fig. 5, 153, 154, 155, 156, 157, 158, 159, 182, the magnet 183 of the ten translator, the contact point 184 of the ten selector, the tip of the trailer-brush 174 of the ten selector, now resting thereon, to wire joint 185 and ground 186, Figs. 6 and 14.
- The effect of this current is, to energize one of the ten translator magnets 183 and release the pawl 187, which makes contact with the ratchet 188 of the ten translator and stops the same in the position selected.
- When the trailer-brush 189 of the unit selector has reached its selective position, a circuit is established as follows:—
- From ground 57, Fig. 4, to wire joint 56, the battery 55, wire joints 54, 53, 52, 51, Fig. 4, 109, Fig. 5, 153, 154, 155 to the tip of the trailer-brush 189, of the unit selector, the contact point 190 on which the same is now resting, one of the magnets 191, of the unit translator of the terminator, the contact point 192, now making contact with a con-

tact spring 193 of the pawl 187 of the ten translator, wire joints 194, 195, the magnet 196, wire joints 197, 198, 199, 185, and to ground 186, Fig. 6 and Fig. 15.

5 The effect of this current is, to energize one of the magnets 191 of the unit translator, release its pawl 200 and stop the ratchet 201 of the unit translator in the position selected.

10 Simultaneously, the magnet 196 is energized and attracts its armature 202. This armature acts upon a group of springs 203, and by making contact with the left spring of the group, a circuit is prepared as follows:—

15 From ground 186, Fig. 6, to wire joints 185, 199, 198, the relay 204, to ring-back controlling magnet 205, to armature 202 of magnet 196, the left spring of the group of springs 203, the contact ring 206 of the unit busy test, the brushes of the trailer arm 207, a contact point 208 upon which the outer brush will be resting and which point will correspond to the position selected by the ratchet cylinder 201, to the contact ring 209 of the ten busy-test, the brushes of the trailer arm 210, a contact point 211, upon which the outer brush will be resting and which point will correspond to the position selected by the ten ratchet cylinder 188. It must be kept in mind that the busy-test trailers 207, 210 are secured to and mounted on the shaft carrying the corresponding ratchet cylinders 188, 201 of the 20 terminators translators.

The circuit continues from contact point 211 to armature 212 of the individual line relay 42, Figs. 4 and 16.

25 Should the line of the called subscriber be busy, the line relay 42 would be energized and its armatures 41 and 212 would be attracted and the circuit just described would be continued through the armature 212, of the individual line relay 42, to the contact point 213, wire joints 214, 54 to the battery 55, wire joints 56 and ground 57, Fig. 4 and Fig. 16.

30 Should the line of the called subscriber be not busy, the circuit just described would not be closed and the magnets 204 and 205 would not be energized.

35 When magnet 196 attracts the armature 202, and has pressed the left hand contact of the contact group 203 to the insulated middle contact, it further presses this middle contact to the right hand contact and closes the following circuit:—from ground 186, Fig. 6, wire joints 185, 199, 198, 197, relay 215, to the middle contact of the group of contacts 203, the right hand contact of the same group, wire joints 195, 194, pawl 200 of the unit translator, now in contact with a tooth of ratchet cylinder 201, to wire joints 182, 159, 158, 157, 156, 155, 154, 153, Fig. 6, wire joint 109, Fig. 5, wire joints

51, 52, 53, 54, to battery 55, wire joint 56 to ground 57, Fig. 4 and Fig. 16.

The effect of current passing over this circuit is to energize the relay 215, which attracts its armature 216 and closes the following circuit:—

From ground 186, Fig. 6, to wire joints 185, 199, to contact point 217 now in contact with the armature 218 of the relay 204, through that armature, to contact point 219 now in contact with armature 216 of the relay 215, through that armature to the clutch-magnet 220 of the shuttle-lifting device of the terminator and wire joints 156, 155, 154, 153, Fig. 6, wire joint 109, Fig. 5, wire joints 51, 52, 53, 54 to battery 55, wire joint 56, to ground 57, Figs. 4 and 16.

The energization of the clutch magnet 220 of the terminator results in releasing the shuttle-lifting mechanism 224 of the terminator, causing one of the terminator shuttles 225 to make contact with the selected line-terminal 223 of the subscriber's line leading to the called subscriber.

At this moment, complete connection is established between the instruments of the calling and the called subscriber. As stated before, the called subscriber in the present case is connected to the same exchange-section as the calling subscriber and it is obvious that the terminator through which this connection is established, may belong to any other exchange-section of the entire system.

The ringing circuits used for ringing-forward to the called subscriber and ringing-back to the calling subscriber will be more fully described hereinafter. When both subscribers, the calling subscriber as well as the called subscriber, have taken their receivers off the hook, talking connection is established between the instruments of the calling subscriber and the called subscriber as follows:—

40 Commencing at the upper end of the battery, 55, Fig. 4, wire joints 54, 53, 52, 51, Fig. 4, 109, Fig. 5, 153, 154, 155, 156, 157, 158, Fig. 6, to and through the upper winding 227, of the impedance coil 228, to junction point 229. The circuit divides at this point and its branches will be followed out later.

45 From the lower end of the battery 55, Fig. 4, another branch of this circuit leads over wire joints 56, Fig. 4, 173, Fig. 6, to and through the lower winding 230 of the impedance coil 228, to junction point 231, where the circuit divides again into two branches as hereinafter will be described. It will thus be seen that a difference of potential exists between the two points 229 and 231, and it will now be shown how this difference of potential is utilized to feed the transmitters of the calling and called subscriber.

The circuit leading to the instrument of the called subscriber starts at junction point 229, over stationary contact-point 241 of the talking battery switch 242, the right-
 5 hand blade 243 of the movable arm of said switch, to contact spring 244, Fig. 6, at the terminator, the lower shuttle ribbon 245, the middle contact brush 246 of the terminator shuttle 255, the middle terminal
 10 of the line-terminals 226, wire joint 247, over line B, Fig. 4, the terminal 248 of the called subscriber's sender, the contact spring 249, over the contact-lever 250, the contact spring 251, the terminal 252, wire joint 253,
 15 the receiver 254, the transmitter 255, the contact point 256 now in contact with the receiver hook 257, over this receiver hook to the terminal 258, over line A, leading to the terminator of the exchange-section to
 20 which the called subscriber is connected, wire joint 402, Fig. 4, to the upper terminal of the terminal group 226, Fig. 6, the upper contact brush 259 of the terminator shuttle 225, now in contact therewith, the upper
 25 shuttle ribbon 260, the contact spring 261, wire joint 395, talking-battery cut-in relay 396, wire joint 397, to the left blade 262 of the movable arm of the talking-battery switch 242, to the stationary contact spring
 30 263 in contact therewith, and to the junction point 231. A non-inductive resistance 398 is in shunt with the relay 396, to be used by the voice current. It is obvious that, since potential exists between the points 229 and 231, current will be fed to the transmitter 255 of the called subscriber also.

The circuit leading to the instrument of the calling subscriber is as follows:—

From wire joint 229, Fig. 6, to the upper-
 40 most spring of the upper group of the selector controller contacts 167, to the middle spring of the right hand group of the ring-back contacts 168, through the movable spring of that group, to the middle contact
 45 of the trunk-terminals 152 of the pilot, the contact brush 116 of the pilot shuttle 93, the lower shuttle ribbon 115, the contact spring 114, to the upper spring of the lower group of the pilot ring-back contacts 96,
 50 through the movable spring now in contact therewith, to the contact spring 113, Fig. 4, of the originator, the lower shuttle ribbon 112, the middle contact brush 111 of the originator shuttle 81, the middle line terminal 82, forming the exchange terminal of the line A, wire joints 110, 40, over line A to the subscriber's sender, the sender terminal 39, Fig. 1, of line A, wire joints 38, 37, 36, 232, the contact spring 25, the lever
 55 21 now in contact therewith, the contact spring 24, the terminal 233 at the sender, the wire joint 234, to the receiver 235 of the calling subscriber, the transmitter 236, the contact point 237 now in contact with the receiver hook 238 in its up-position,

through that receiver hook, the wire joints 239, 240 of the line B leading from the calling subscriber to the exchange, the wire joint 88, Fig. 4, the upper terminal spring of the terminals 82, the contact brush 125
 70 of the originator-shuttle 81 now in contact therewith, the upper shuttle ribbon 89, the contact spring 90, the wire joints 91, 392, through the clearing-out magnet 393, the wire joints 394, 95, to the movable spring 75 of the upper group of the ring-back contacts 96, Fig. 5, to the upper spring thereof, the contact spring 97, the upper shuttle ribbon 98 of the pilot, the upper contact brush 101 of the pilot shuttle 99, the upper line-terminal 152 of the trunk-line leading to the exchange-section of the called subscriber, the movable spring of the left-hand group of the ringing contacts 168, the left-hand
 80 spring of that group, the movable spring 85 of the lower group of the selector controlling contacts 167, the upper spring of that group, the armature of the talking-battery cut-in relay 396, the contact point 400, now in contact with the armature 399, as the relay 90 has become energized over the circuit of the called subscriber just described, to the junction point 231. Since, as already shown, potential exists between the point 229 where this last described circuit is started, and point 231, where it ended, it is plain that the transmitter 236 of the calling subscriber will receive current.

Owing to the presence of the impedance coil 228, in both the circuits now described, 100 which form an obstacle to the passage of the voice currents, these latter take the following path:—

From the transmitter 236 of the calling subscriber, Fig. 1, to the contact point 237, 105 the receiver hook 238, wire joints 239, 240, Fig. 1, over line B, wire joint 88, Fig. 4, the upper terminal 82 at the originator, the upper contact brush 125 of the originator shuttle 81, the upper shuttle ribbon 89, the contact spring 90, wire joints 91, 392, the clearing-out control magnet 393, wire joints 394, 95,—there is a non-inductive resistance 401 in shunt with the magnet 393,—the movable spring of the upper group of the ringing contacts 96 of the pilot, Fig. 5, the upper spring of that group, the contact spring 97, the upper shuttle ribbon 98 of the pilot shuttle 99, the upper terminal of the trunk-line terminals 152, the movable 110 spring of the left-hand group of the ring-back contacts 168, Fig. 6, the left-hand spring thereof, the movable spring of the lower group of selector-controller contacts 167, the upper spring of the same, the armature 399 of the talking-battery cut-in relay 396, the contact point 400 now in contact therewith, the junction point 231, the stationary contact 263 now in contact with the contact 262 of the movable arm of the talk- 115

ing-battery switch 242, the wire joint 397, the talking-battery cut-in relay shunt 398, wire joint 395, the contact spring 261, the upper shuttle ribbon 260, the upper contact brush 259 of the terminator shuttle 225, now in contact with the upper terminal of the called subscriber's terminals 226, wire joint 402, Fig. 4, over line A, to the called subscriber's instrument, the instrument terminal 258 the receiver hook 257, the contact 256, the transmitter 255 the receiver 254, wire joint 253, the instrument terminal 252, the contact spring 251, the contact lever 250, the contact spring 249, the sender terminal 248, over line B, wire joint 247, the middle terminal of the called subscriber's line-terminals 226, the middle contact brush 243 of the terminator shuttle 225 now in contact therewith, the lower shuttle ribbon 245, the contact spring 244, the contact blade 243 of the movable arm of the talking-battery switch 242, the stationary terminal 241 now in contact therewith, to the junction point 229, the upper spring of the upper group of the selector controller contacts 167, the movable spring thereof, the left-hand spring of the right-hand group of the ringing contacts 168, the movable spring thereof, the middle terminal of the trunk-line terminals 152 of the pilot, Fig. 5, the middle contact brush 116 of the pilot shuttle 99, the lower shuttle ribbon 115, the contact spring 114, the upper spring of the lower group of the pilot ring-back contacts 96, the movable spring thereof, the contact spring 113 at the originator, Fig. 4, the lower shuttle ribbon 112, the middle contact brush 111 of the originator shuttle 81, the middle terminal of the calling subscriber's line-terminals 82, wire joints 110, 40, over line A, to the calling subscriber's instrument, Fig. 1, the sender-terminal 39, wire joints 38, 37, 36, 232, to the contact spring 25, the contact lever 21, the contact spring 24, the instrument terminal 233, the wire joint 234, the receiver 235, back to the transmitter 236, where this circuit was commenced, Figs. 1, 4, 5, 6 and 17.

Pilot shuttle.

The selection of an idle shuttle in the originator has already been described, and, as stated hereinbefore, it is one of the offices of the present invention to trace the link circuit of which this originator-shuttle forms a part, to the corresponding pilot-shuttle. This is accomplished by devices illustrated in Figs. 26, 40 and 42. Referring to Fig. 26, 320 indicates the starting lever of the originator-shuttle which has been pushed-back mechanically by one of the dogs 321 of the originator-shuttle selector, as heretofore described. The vertical arm of the starting lever 320 thereby makes contact with a contact-spring 364, electrically

connected to one of twelve shuttle-selector magnets 365 in the pilot of the same exchange-section. When contact is made with the contact-spring 364, an electrical circuit is closed as follows:

From ground 366, Figs. 4 and 26, wire joint 378, to the starting lever 320, the contact-spring 364, through the magnet 365, Fig. 5 and Fig. 26, wire joints 367, 108, 109, Fig. 5, 51, 52, 53, 54, through battery 55, wire joint 56, to ground 57, Fig. 4.

The energization of one of the magnets 365, caused by the closing of this circuit, just described, results in the attraction of the armature 368 of that magnet which, with its lever 369, causes the tripping of the starting lever 320 of the shuttle-action of the pilot-shuttle 99. The starting lever of the pilot-shuttle having released the actuating lever of the pilot-shuttle, places the lifting-tooth of the same into the path of the shuttle-lifting plate of the working-beam of the pilot, so that this shuttle may be lifted into contact with one of the trunk-line terminals at the pilot.

The originator-shuttle will, in the meantime, have been lifted into contact with the line-terminals of a calling subscriber, and it becomes necessary to prevent the energization of another of the pilot-shuttle selector-magnets 365 until the originator-shuttle has been entirely lifted, and also the pilot-shuttle brought into contact with a trunk-line terminal. For doing this, the shaft 326, Figs. 26 and 40 carries at its end a ratchet 371, and a pawl 372 is adapted to engage with the teeth of this ratchet and hold the same in a position corresponding to the last shuttle selected by the originator-shuttle selecting devices illustrated in Fig. 40, until the pilot-shuttle has been lifted.

For the purpose of bringing this pawl into engagement with a tooth of this ratchet 371, a circuit is closed by the starting lever 320 of the pilot-shuttle, as follows:

From ground 373, Fig. 5 and Fig. 26, to the starting lever 320 of the pilot-shuttle, now, in contact with the contact-spring 374, to a shuttle-protecting magnet 375 at the originator, Figs. 4, 26 and 40, wire joints 52, 53, 54, through battery 55, wire joint 56, to ground 57.

The energization of the magnet 375 causes the attraction of its armature 376, forming a detent for the pawl 372, which pawl, under the action of a spring, not shown in the drawings, is placed against the ratchet 371 and brought into engagement with one of its teeth, holding the ratchet until the pawl is restored by means of the connecting rod 377, actuated by the lever 333, Fig. 32, against which the cross-head 300 is acting when the working-beams complete a full stroke.

It will be seen, therefore, that the shuttle

so selected in the pilot depends directly upon the shuttle selected in the originator, and it forms the end of the line extended from a calling subscriber to the pilot.

5 Before dwelling upon the selection of the terminator-shuttle, it will be necessary to describe the manner of connecting the pilot of an exchange-section with the terminator of the same or other exchange-sections.

10

Trunking.

Before going into the details of the operations of the busy-test, ringing- and clearing-out devices, it is thought opportune to 15 consider the means for interconnecting or trunking between the pilot of one and the terminator of the same exchange-section as well as the terminators of other exchange-sections. As stated heretofore, the present 20 system has some similarity with the so-called "Sabin & Hampton express system," which latter comprises, as it were two divided boards and an auxiliary or intermediate board. The Figs. 28 and 29 of the drawings, which should be considered together, 25 represent diagrammatically the principle used for trunking in the present invention. It will be remembered that the present invention employs a number of link-circuits, 30 less than the number of subscribers connected to an exchange-section, i. e. twelve per cent of the entire number of subscribers, and Figs. 28 and 29 illustrate, how to wire a system of two thousand subscribers so as 35 to equip one exchange-section or an entire exchange with a higher percentage of facilities than another. This percentage may be determined for each case or for each exchange, according to the actual traffic taking 40 place between this exchange and any other exchange.

The percentage of trunks, when once decided upon, need not remain the same, but may be varied and adapted to conditions, if 45 such should become necessary, without all interfering with the operating mechanism of an exchange, and only slightly interfering with the wiring.

If it should be found that a particular 50 exchange-section has an insufficient number of available trunks going in a certain direction, it is possible to increase this percentage of trunks, as long as there are other exchange-sections to which the lesser number 55 of trunks, forming the difference between the first and the entire number of trunks, would be sufficient, or as long as the total trunk-capacity is not needed.

The principle of trunking, illustrated in 60 Figs. 28 and 29 of the drawings, is thought to be broadly new, and it appears to be the only possible system which can readily be changed to comply to the constantly changing conditions in traffic of an exchange operating under commercial conditions.

The figures of the drawings, just referred to, illustrate only one trunk-line leading from the pilot of an exchange-section to the terminator of the same exchange-section or any other exchange-section, although it 70 is obvious that, as an entire metallic circuit is employed in this exchange, two lines are used which end in two terminal-strips. Also a third or safety-strip is present, as illustrated in Fig. 39, which shows the three contacts forming the line-terminal of a subscriber or trunk.

The terminal-end of the trunks is illustrated, for convenience sake, in the form of a commercial plug located below the pilot-board of its exchange-section, which pilot-board consists of ten sub-divisions of ten lines each, located one above the other and represented by heavy horizontal lines. There are ten vertical sets of strips, shown 80 side by side, representing, respectively, the pilot terminal-boards of ten exchange-sections forming an entire exchange of one thousand lines. The multiple connections already referred to in the prior parts of the 85 specification, between the contact-strips of the several switch-board sections, are shown by lighter lines, interconnecting the heavier lines of the terminal-strips.

Fig. 29 illustrates the trunk-lines of another exchange of ten sub-sections of one hundred subscribers each, and shows its interconnection with the plugs in its own terminators as well as the connection with the exchange illustrated in Fig. 28.

It should be kept in mind that the shuttles, intended to make contact with the terminal-strips shown in Figs. 28 and 29, are the pilot-shuttles and are not present in these figures. The shuttles illustrated, are the terminator-shuttles and are intended to make contact with the called subscriber's terminals in the terminator, not shown in those figures.

Comparing the Fig. 28 to the Fig. 29, it 110 will be seen that, for the first, the arrangement of the pilot-terminal boards is not the same and differs materially. It is to be seen, for instance, that the terminal-boards 115 of the pilots of the ten exchange-sections, forming the entire exchange, are apparently divided into two groups. All of the terminal-strips in the five terminal-boards of one group are in multiples, as clearly seen, whereas the terminal-strips of one group of five in relation to the terminal-strips of the other group of five are not all in multiples, but only a certain portion of the same are multiplied straight through. For instance, counting from the bottom of each group of terminal-strips on Fig. 28, it will be seen that the third, fourth and fifth terminal-strip and the eighth, ninth and tenth terminal-strip are multiplied all the way through, 120 whereas the first and second terminal-strips 125 are not. The same is true of the other group of five, although the arrangement is not so clearly seen. The same is true of the terminators, 130 although the arrangement is not so clearly seen. The same is true of the other group of five, although the arrangement is not so clearly seen. The same is true of the terminators, 135

and the sixth and seventh terminal-strips, respectively, are multiplied only to a group of five exchange-sections. In Fig. 29, however, all the terminal-strips are multiplied throughout the entire ten exchange sections.

The terminal strips 1 and 2 and the terminal strips 6 and 7 of the five sections to the left in Fig. 28, are connected by independent lines with the rest of the exchange in such a manner that the lines leading from the terminal strips 1 and 2 terminate in plugs in the center of the bank of plugs allotted to each section in every alternate section, while the lines leading from the terminal strips 6 and 7 terminate in like manner in plugs in the remaining sections.

The connections, just described, cause a difference of capacity of the two exchanges, illustrated in Figs. 28 and 29, resulting in a greater percentage of available facilities for trunking in the exchange represented in the Fig. 28 than in that in Fig. 29, and the arrangements are such that the exchange in Fig. 28 is the busier of the two in the ratio of seven to five. It is obvious that this ratio is entirely arbitrary, and any ratio within the capacity of the exchange, or not larger than one to twelve, can be established without materially disturbing the wire connections, and without in the least disturbing the apparatus.

Although there is the same number of shuttles and terminal-strips present in both exchanges, it will be seen that in the exchange illustrated in Fig. 29, there are ten points for each trunk where a connection can be made. In the exchange illustrated in Fig. 28 some trunks are connected all the way through, as stated, the third, fourth, fifth and the eighth, ninth, tenth from below; they have the same ratio of being busy as all the trunks in Fig. 29, while the trunks one, two, and six, seven have only five multiples and can, therefore, be connected only at five points, in other words, the chances of these latter trunks being busy are only one half of the trunks in Fig. 29, or those of Fig. 28 which are connected all the way through.

It will thus be seen that there are at any time more available trunks in the exchange Fig. 28 than in that of Fig. 29, and that the exchange illustrated in Fig. 28, although having the same number of shuttles and terminal-strips, can handle a relatively greater business than that represented in Fig. 29.

Terminator shuttle.

The shuttle in the terminator of an exchange-section is brought into operation by a device comprising a ratchet cylinder similar to the ratchet cylinders used in the translators of the originator, the pilot and the terminator, which ratchet-cylinder in the

terminator is caused to stop at a predetermined position corresponding to the trunk-line selected in the pilot, to which the line of a calling subscriber has been extended, for the purpose of bringing about maintenance of rotation of the calls coming into the terminator.

This ratchet-cylinder 379, Fig. 41, is provided with twelve stops 380, that is, one stop for each of the twelve shuttles of the terminator. It is secured to a shaft frictionally connected to the common power-device, which shaft carries the trailer-arm 166, having sets of contact-brushes 381, 382, 383. The contact-brushes are adapted to glide upon commutators 170, 165 and 384 and upon contact-rings 171, 163 and 385, respectively. The commutators are illustrated also in Fig. 6 of the drawings, at the upper left-hand corner and the upper right-hand side.

Below the ratchet-cylinder 379, there are arranged twelve magnets 386, adapted to attract armatures 387, acting as detents for pawls 388, capable of dropping into the path of the stops 380 on the ratchet-cylinder 379, and stopping that ratchet-cylinder at any one of twelve different positions, thereby determining also the position of the contact-brushes 381, 382, 383 in relation to the commutators 170, 165 and 384. The resetting of the pawls in this device is brought about through the connecting-rods 389, 389' and a lever 390 acting upon the shaft of the pawls 388 similar to the resetting of the corresponding pawls in the ratchet-cylinders of the translators, when one of the working-beams of the shuttle-lifting devices at the terminator passes the lower sprocket-gears.

The connection of the trunk-line terminals at the pilot of a sub-section with the shuttles of the terminators of the same or another sub-section, has been described heretofore, and it is, therefore, obvious that each trunk-line terminal selected at a pilot, determines the shuttle which forms the end of the line of a calling subscriber now extended to a terminator. The operation of the ratchet-cylinders, therefore, is to pick out that shuttle at the terminator, which belongs to the trunk selected at the pilot.

The operation of this ratchet-cylinder is as follows:

When the pilot shuttle 99 has made contact with the terminals 152 of the trunk-line selected, the lower contact-brush 403 of the pilot shuttle makes contact with the lower terminals of the trunk-terminals 152 and causes the establishment of the following circuits:—

From ground 404, Fig. 4 and Fig. 27 to the clearing-out control-relay 94, to the lower contact-brush 403 of the pilot shuttle 99, the lower terminal of the trunk-line terminal 152, now in contact with that con-

tact-brush, Figs. 5 and 27, the wire joint 405, through one of the twelve magnets 386 of the ratchet-cylinder 379, the wire joints 153, 109, 51, 52, 53, 54, through battery 55, the wire joint 56, to ground 57, Fig. 4.

The effect of current passing over this circuit is, to energize one of the magnets 386, which attracts its armature 387 and releases the pawl 388. This pawl, in dropping into the path of one of the stops 380 of the ratchet-cylinder 379, causes the same to stop in a position depending upon the trunk-line selected at the pilot and belonging to that set of trunk-lines connecting this terminator with that pilot. The simultaneous stopping of the trailer-arm 166 results in holding the contact-brushes 381, 382, 383 on corresponding contact-points 170, 165 and 384, whereby a circuit is closed as follows:—

From ground 406, Fig. 27, to the contact-ring 385, the inner brush of the contact-brushes 383, the outer brush of the same, now resting on contact-point 384, one of the shuttle-selecting magnets 365 at the terminator, the wire joints 157, 156, 155, 154, (Fig. 6) 109, (Fig. 5) 51, 52, 53, 54, through battery 55, the wire joint 56, to ground 57 (Fig. 4). The current flowing over this circuit, causes the energization of one of the shuttle-selecting magnets 365 (Figs. 26 and 42), which, in attracting its armature 368, Fig. 42, causes the starting lever 320 of the shuttle-action of the terminator shuttle, to release the actuating lever 316, which is forced forward, so as to place the lifting-tooth 317 into the path of the lifting-plate 298 of the terminator-shuttle lifting-mechanism.

Until now it has been described, how the shuttles in the different sets of operating mechanism of a self-acting exchange, the originator, the pilot and the terminator, are selected, provided, however, they are not "busy" or, in other words, are not engaged in making connection between a calling subscriber and a called subscriber.

In this latter case, a test must be made for "busy", but this problem of testing for "busy" will not be met with in the originator of an exchange-section, because each subscriber knows when his line is busy, and will not send a signal, calling another subscriber, until he has completed his conversation with a prior caller. The first part of an exchange-section where it will become necessary to provide means for a "busy test" is the pilot, in which, as stated hereinbefore, the group-signal is received, identifying the trunk-line leading to the exchange-section with which the called subscriber is connected. It has been stated and has been described that from each pilot there lead a number of trunk-lines to the terminator of the same exchange-section and also to the terminators of other exchange-sections. The number of these trunk-lines leading to

the different terminators depends upon the number of connections or the amount of traffic met with between the pilot of an exchange-section and the terminators of the respective exchange-sections. For the purpose of ascertaining whether or not a trunk-line or line of a called subscriber is busy, the following devices are provided.

Busy tests.

75

The pilot busy-test is illustrated in Fig. 18 of the drawings. Having in view the scheme used for trunking between the pilot and the terminator of the same exchange-section and the pilot of one exchange-section and the terminator of other exchange-sections, it will be remembered that in the example shown, at least five trunks lead from one pilot to a terminator, and the function of the group-signal is, practically, to select a trunk-line identified by the digit of the thousand-numeral and a digit of the hundred-numeral which in the present case necessitates a somewhat different selector for the hundred-numerals than is used for the other numerals of the call-number of a subscriber.

As will be seen in Fig. 18, the contact-points of the hundred-selector at the right-hand end of the figure, are connected together into two groups, one group comprising the odd numbers and the other group comprising the even numbers. Each of the groups is connected to a trunk-control relay 136, the winding of which is connected over wire joints 135, 128, to ground 127. To each trunk-control relay is connected a wire leading to and interconnecting a group of five translator-magnet control-relays 408, and from each of these relays connection is made to one of a number of contact-rings of a commutator secured to the shaft of the thousand-translator ratchet-cylinder 134. This pilot-busy-test commutator 410 is furthermore provided with a series of ten radially arranged groups of contact-points 411, and each of the contact-points of these groups is connected, respectively, to the lower terminal of the trunk-terminals 152 at the pilot. The trailer-arm 412 is normally rotating with the shaft of the thousand-translator ratchet-cylinder 134 and is caused to stop on a row of contact-points 411, when one of the pawls 133 of the thousand-translator ratchet-cylinder is forced into the path of one of the teeth and determines, as herein described, the position of the vertical cylinders 280 and, thereby, the height to which the pilot-shuttle 99 is to be lifted, in order to make contact with the trunk-line terminal desired.

When now the selective impulses at the hundred selector are received, and the trailer-brush 139 is caused to stop at a contact-point corresponding to the digit of the

125

130

hundred-numeral of the call-number of a subscriber, a circuit is closed, in the first place through the trunk-line relay 136, provided, however, the thousand-translator has 5 been stopped in the position selected. This circuit is as follows:—

From ground 57, Fig. 4, to wire joint 56, through the battery 55, the wire joints 54, 53, 52, 51, 109, 108, 107, 132, 140, to the 10 thousand-translator ratchet-cylinder 134, one of the pawls 133 now in contact therewith, the tip of the trailer-brush 139 of the hundred-selector, one of the contact points 138 upon which this tip is now resting, the 15 wire joint 137, the trunk-control relay 136, the wire joints 135, 128, to ground 127.

The effect of current passing over this circuit is to energize the trunk-control relay 136, which, in attracting its armature 141, 20 closes the following circuit:—

From ground 127, Fig. 5 and Fig. 18, to the wire joints 128, 135, the armature 141 of the relay 136, the contact-point 142, now in contact with the armature, the upper contact-blade of contacts 143, the contact-point 25 144 now in contact therewith—provided none of the hundred-translator-magnets control-relays are energized—through the translator-magnets 145, the wire joints 140, 132, 107, 30 108, 109, 51, 52, 53, 54, through the battery 55, the wire joint 56, to ground 57.

The effect of current flowing over this circuit is to energize half of the hundred-translator-magnets at the pilot. Remembering 35 that the stops on the ratchet-cylinder 148 are arranged in a helix, it is obvious that only one of the pawls caused to drop forward by the energization of the magnets 145, will become effective and will stop the 40 hundred-translator ratchet-cylinder 148, thereby finally determining the height to which the pilot shuttle 99 is to be lifted, in order to make contact with the trunk-line selected.

It will now be shown, how these same devices operate as a busy-test. Provided, that one of the shuttles 99 at the pilot has already been lifted into contact with a trunk-line, a circuit will have been closed at the moment 50 when a pilot-shuttle 99 makes contact with a trunk-terminal as follows:—

From ground 404, Fig. 4 and Fig. 18, through the clearing-out control-relay 94 the lower contact-brush 403 of the pilot-shuttle 99, Fig. 5, the lower terminal of the trunk-line terminals 152 now in contact therewith, the wire joint 413, one of the series of contact-points 411 at the pilot-busy-test commutator 410, the bridged contact-brushes of the 55 trailer-arm 412 now resting thereon, to one of the contact-rings 409 of this commutator, one of the pilot-translator-magnet control-relays 408, the wire joint 137, to a contact point 138 on the hundred-selector, the tip of 60 the trailer-arm 139 now resting on this con-

tact-point, on of the pawls 133 of the thousand-translator now in contact with the ratchet-cylinder 134, through this ratchet-cylinder 134, the wire joints 140, 132, 107, 108, 109, 51, 52, 53, 54, through battery 55, the 70 wire joint 56, to ground 57, Fig. 4.

The effect of a circuit so closed by any of the pilot-shuttles is to energize one of the hundred-translator-magnet control-relays 408 which, in attracting its armature, removes the contacts 143 from contact with the upper contact-point 144, but at the same time makes contact between its lower contact-blade and the lower contact-point 414, for a purpose hereinafter to be described. 80 Through the removal of the upper contact-blade 143 from contact-point 144, it becomes impossible to energize the corresponding hundred-translator-magnet and, therefore, the ratchet-cylinder 148 cannot stop 85 in a position corresponding to this other magnet. When, however, a succeeding call comes in, it will operate, as described hereinbefore, to energize all the remaining hundred-translator-magnets, the pawl of only 90 one of which, of course, can become effective in again stopping the ratchet-cylinder 148 at a position corresponding to the hundred-digit of a call-number of a subscriber. 95

The resetting of the pawls of the thousand-and hundred-ratchet-cylinders takes place in exactly the same way as hereinbefore described, through the operation of the working-beams passing the lower sprocket-wheels. In case all five trunk-lines leading to one and the same terminator of an exchange-section should be engaged or be “busy”, all five of the hundred-translator control-relays 408 will be energized, their 100 armatures will be attracted and the contact-brushes 143 will be removed from the upper contact-points 144 and will come in contact with the lower contact-points 414, so that a new circuit will be established as follows:— 110

From ground 127, Fig. 5 and Fig. 18, the wire joints 128, 129, the lower blade of the contacts 143, the contact-point 414, the lower blade of the next contact 143, the next lower contact-point 414, etc., through all the hundred-translator-magnet control-relays, to the ring-back control-magnet 415, the wire joints 367, 108, 109, 51, 52, 53, 54, through battery 55, the wire joint 56, to ground 57. 115

The effect of current passing over this circuit is to energize the ring-back control-magnet 415 for a purpose to be described when the ringing mechanism is hereinafter considered. 120

It will be seen from the description of the pilot-busy-test that this apparatus not only operates to test whether a trunk-line is already engaged or not, but also operates as a trunk-line selector, i. e., determines which one of the idle trunk-lines leading to the ter- 125

minator of the exchange-section of the called subscriber shall be used for extending a line, already established between a calling subscriber and the pilot, over this trunk-line 5 so selected to the terminator of the exchange-section with which the called subscriber is connected.

It has been pointed out that the hundred-selector 353, Fig. 5, differs from the units, 10 tens and thousands selectors in having the contact points 138 connected in two groups rather than individually. In the present case, the exchange is organized on a 2000 line basis. As so arranged, there would be 15 two exchange sections corresponding to each of the ten digits of the thousand-numerals of the group signals, one being the "odd" exchange section, and the other the "even" exchange section, making a total of twenty. 20 Obviously, if the exchange were organized on a 10,000 line basis, then each of the contacts 138 of the selector 353 would be wired to a separate relay 136, and to separate corresponding groups of relays 408. Obviously, also, when organized on a 2000 line 25 basis, it would be sufficient to utilize merely the first and second contacts 138 of the selector 353, connecting these contacts to separate relays 136 with separate associated groups of relays 408, leaving the contact points beyond the second disconnected. In this case, the group signals would utilize as hundred-numerals only the digits 1 and 2, and the group signals would be 11, 12, 21, 30 22, 31, 32 and so forth, giving a total of twenty exchange sections in the system. Many variations may be made in the arrangement of the hundred-selector and the contact members to which it relates, and I 35 do not wish to be limited to the specific arrangement here illustrated.

In contradistinction of this device, the busy-test of the terminator has only one function, i. e., to find out whether the line 40 of the called subscriber is busy or not. This line may be busy in two ways, i. e., it may be busy as a calling line by having an originator-shuttle connected to its line-terminals at the originator of the exchange-section with which it is connected, or it may be busy as a called line, in which case a terminator-shuttle will be connected to its line-terminals at the terminator of the exchange-section with which it is connected.

55 The line-terminals at the originator and the line-terminals at the terminator are connected in multiples, i. e., each of the contact-strips of the line-terminals, the upper one, to which line B is connected, the middle one, to which line A is connected, and the lower one, which acts as a guard, all of these three are connected in multiple, respectively, to the upper, the middle and the lower contact-strips of the line-terminals at the terminator. 60

65 It has been said hereinbefore that when-

ever either an originator-shuttle or a terminator-shuttle is connected to line-terminals at the originator or the terminator, a circuit is closed which energizes the individual line-relay of a subscriber, whereby 70 an armature of this line-relay is attracted—as stated before, the only movable part in an entire exchange-section which is individual to a subscriber. The practical function of the busy-test of the terminator, 75 therefore, is to establish the fact whether this individual line-relay of a subscriber is energized or not.

The circuit for energizing the individual line-relay of a subscriber, in case an originator-shuttle is in contact with the line-terminals at the originator, has already been described, and it remains to be shown in what way this individual line-relay is energized, in case a terminator-shuttle is in contact with the line-terminals at the terminator of a called subscriber. This energization of the individual line-relay in the latter case takes place over the following circuit:—

From ground 404, through the clearing-out control-relay 94, to the lower contact-brush 403 of the pilot-shuttle 99, Fig. 5, the lower terminal of the trunk-line terminals 152 at the pilot now in contact therewith, the wire joints 413, 405, to the lower contact-brush 416 of the terminator-shuttle 225, the lower terminal of the line-terminals 226 at the terminator of the calling subscriber, the wire joint 417, Fig. 4, the individual line-relay 42 at the originator of the called subscriber, the wire joints 418, 54, through battery 55, the wire joint 56, to ground 57.

The current passing over this circuit energizes the individual line-relay 42 of the called subscriber and also the clearing-out 105 control relay 94, as both of these relays are arranged in series in this circuit.

The effect of this current on the individual line-relay 42 is to energize the same and attract its armature 212, closing a circuit which already 110 has been described at the beginning of the operation when the originator-shuttle 81 makes contact with the line-terminals 82 at the originator of a calling subscriber. The simultaneous energization of the clearing-out control-relay 94 results in the attraction of the armature 93, which breaks the contact with the contact-point 92 and throws the clearing-out magnet 393 into the circuit 115 passing from the point 95 through the windings of the magnet 393 to the point 91, thereby energizing the clearing-out magnet 393 which attracts its armature 419 and stops the rotation of the clearing-out device 420 before the same has made a complete revolution and returned to its normal position.

It now remains to be described in what way the terminator-busy-test, illustrated in Fig. 16, will operate in case the line of the called subscriber is busy, whether this means 130

"busy" as a calling subscriber, or as a called subscriber.

Through the attraction of the armature 212 of the now energized individual line-
5 relay 42, a circuit has been extended from ground 57 over this armature to the terminator-busy-test as follows:—

From ground 57, Fig. 4, to wire joint 56, through battery 55, the wire joints 54, 10 214, the contact-point 213, the armature 212 to one of the points of the radially arranged rows of contact-points 211 of the terminator-busy-test. The trailer-arm 210 of this busy-test, which is on the same shaft with the ten-
15 translator-ratchet-cylinder 188, has been stopped upon this row of contact-points 211 and the circuit, therefore, is extended over the bridged contact-brushes of the trailer-arm 210 to one of the contact-rings 209 and 20 to one of the ten contact-points 208 of the unit-busy-test. The trailer-arm 207 of the unit-busy-test which is on the same shaft with the ratchet-cylinder 201 of the unit-
25 translator, has been stopped with this ratchet-cylinder in a certain position, so that its bridged contact-brushes extend this circuit to the contact-ring 206, the left contact-blade of the contacts 203, now in contact with the armature 202 of the energized mag-
30 net 196, to the ring-back magnet 205 at the terminator, Fig. 6 and Fig. 16, the clutch-control-relay 204, the wire joints 198, 199, 185, to ground 186. The circuit of the current which energizes the magnet 196 may be
35 readily traced in Fig. 15.

The effect of this circuit is, to energize the ring-back magnet 205 and the clutch-control-relay 204. The operation of the ring-back-magnet 205 will be described herein-
40 after. The energization of the clutch-control-relay 204 results in the attraction of its armature 218, which breaks the contact with the contact-point 217 and prevents the energization of the clutch-magnet 220, which,
45 therefore, cannot bring the shuttle-lifting mechanism of the terminator into action.

Ringing mechanism.

The ringing operation in the present invention may be divided, first, into the ringing during a successful call and, second, into the ringing during a busy call. The ringing during a successful call consists of ringing the bell of the calling subscriber, notifying him that connection is made with the instrument of the called subscriber, and ringing the bell of the called subscriber, notifying him that talking connection is desired with him.

60 The devices for accomplishing this purpose are illustrated in Figs. 46 and 47 and consists of a normally rotating shaft 421, connected by means of a pulley 422 to the common power-device. Frictionally secured
65 to this shaft and held thereon by suitable

washers, are sets of disks 423, 424, in a number equal to the number of shuttles used in the respective operating devices; in the present case there are employed twelve such sets. The disks 423 are in the form of ratchets 70 having eight teeth, and the disks 424 are continuous, but have a recess 425. The disks 424 are furthermore provided with a pin 426 extending on both sides of the disk near the periphery thereof, and a second pin 427 ex- 75 tending only on one side of the disk, and located diametrically opposite to the location of the first pin.

The sets of disks are normally prevented from rotation by a detent 428, forming one 80 lever-arm of a bell-crank 429, which is also provided in the same number as there are shuttles. These bell-cranks are normally held at their outer end by a detent 311, in engagement with the ratchet 309 of the upper 85 ribbon-tension at the pilot and the termina-
tor.

The pin 426 is capable of acting upon the movable contact of the contacts 168, and also upon clearing-out contacts 430. The 90 pin 427 is capable of acting against one arm 431 of a bell-crank 422, the longer arm of which forms the armature of the retardation coils 228. This lever 422 is also capable of acting on the contacts 241, 263 and 432, 95 433. These contacts 241 and 263 have been described hereinbefore, and the former with the contacts 432 and 433 are illustrated in Fig. 46 of the drawings in a somewhat different way than in Fig. 6, but it will be 100 seen that the cooperation of the same with the lever-arm 242 is substantially the same in both figures.

The circuits used for ringing forward and back are illustrated in Fig. 21, and the 105 first ringing act, being the ringing act to the calling subscriber, takes place as follows:—

When the terminator-shuttle 225 is being lifted, the upper ribbon-tension of the termina- 110 tor winds up the upper shuttle ribbon and the first tooth of the ratchet 309 passing downward during the rotation of the ribbon-tension in the direction of the arrow, indicated in Fig. 46, will force the lever 311 outward, so that the lever 429 is released and is caused to move upwardly by the set of disks 423, 424 acting against the detent 428. This detent is then caused to glide upon the periphery of the disk 425, 115 and the pin 426, pressing against the movable contacts of the contacts 168, will throw the magneto-generator 434 on the line and send alternating current to the bell of the calling subscriber over the following circuits:—

From the upper brush of the magneto-generator to the right-hand contact of the left group of contacts 168, the movable contact-spring, now in contact therewith and 120

forced against it by the pin 426, over trunk-line B to the upper terminal of the trunk-line-terminals 152 of the pilot, the contact-brush 101 of the pilot-shuttle 99, now 5 in contact therewith, the upper shuttle-ribbon 98, the contact-spring 97, to the upper spring of the upper group of ring-back contacts 96, to the movable spring thereof, now in contact therewith, the wire joints 10 95, 394, through the clearing-out magnet 393, the wire joints 392, 91, the contact-spring 90 at the originator, the upper shuttle-ribbon 89, the upper contact-brush 125 15 of the originator-shuttle 81, the upper terminal of the line-terminals 82 of the calling subscriber, the wire joint 88, over line B to the subscriber's instrument, Fig. 1, the wire joints 240, 239, the bell 435, the condenser 436, the wire joint 234, the instrument-terminal 233, the contact-spring 24, the contact-lever 21, the contact-spring 25, 20 the wire joints 36, 37, 38, the sender-terminal 39, over line A to the originator of the exchange-section of the calling subscriber, the wire joints 40, 110, to the middle terminal of the line-terminals 82 at the originator, the contact-brush 111 of the originator-shuttle 81, now in contact therewith, the lower shuttle-ribbon 112, the contact-spring 113, the movable spring of the lower group of ring-back contacts 96 at the pilot, the upper spring of this group, the contact-spring 114, the lower shuttle-ribbon 115, the middle contact-brush 116 of the 30 pilot-shuttle 99, the middle terminal of the trunk-line-terminals 152, over the trunk-line A to the movable spring of the right-hand group of the ringing-back key 168, to the right-hand spring thereof, and back to the lower brush of the magneto-generator 434, Fig. 6.

The effect of alternating current passing over the circuit is, to ring the bell of the calling subscriber. The disk 424 makes 45 only one revolution and the pin 426, therefore, acts only once against the contact-springs 168, because the detent 428 will enter into the recess 425 at the completion of a complete revolution of the disk 424 and will 50 again be held by the detent 311, which now rests between two teeth of the upper ribbon-tension of the terminator-shuttles.

The ringing-forward to the called subscriber is brought about by the cooperation 55 of the teeth of the ratchet 423 with the lever-arm 431 of the bell-crank 242. This bell-crank will be raised as many times as there are teeth on the ratchet 423, provided, however, that the called subscriber 60 does not take off his receiver when he hears the first or second, etc. ring, in which case, through the act of taking off the receiver, a circuit is closed through the retardation-coils 228, which at the same time attracts 65 the armature, secured to the bell-crank 242,

and prevents that bell-crank from further rising. As stated hereinbefore, this bell-crank operates the ringing-forward keys or contacts by alternately making contact between its movable members 262 and 243, its 70 stationary contacts 241, 263 and 432, 433. By making contact with the stationary contacts 241, 263, battery is thrown on the line and by making contact with the stationary contacts 432, 433, the magneto-generator is 75 thrown on the line over the following circuit:—

From the upper brush of the magneto-generator 434 to the stationary contact-spring 433, the movable contact-spring 262, 80 the wire joint 397, through the battery cut-in relay 396, the wire joint 395, the contact-spring 261, the upper shuttle-ribbon 260, the upper contact-brush 259 of the terminator-shuttle 225, the upper terminal of the 85 terminator-line-terminals 226, the wire joint 402 at the originator, over line A to the instrument of the called subscriber, the sender-terminal 258, the bell 437, the condenser 438, the wire joint 253, the instrument-terminal 252, the contact-spring 251, the contact-lever 250, the contact-spring 249, the sender-terminal 248, over line B to the originator, the wire joint 247, the middle terminal of the terminator line-terminals 226, 90 the contact-brush 246 of the terminator-shuttle 225, the lower shuttle-ribbon 245, the contact-spring 244, the movable contact-spring 243 of the ring-forward contacts, the stationary contact-spring 432 in contact 95 therewith, to the lower brush of the magneto-generator 434.

The effect of the alternating current passing over this line is, as stated hereinbefore, to ring the bell of the called subscriber 100 either as many times as there are teeth of the ratchet 423, or until the called subscriber takes off his receiver.

The ringing operations just described, are the normal operations when both the calling and called subscriber are disengaged, and, therefore, connection can be established between them at once. There are also means provided in the present self-acting exchange 110 for notifying the calling subscriber that 115 connection has not been made with the called subscriber. The reasons for not making connection may be twofold, either, there is no idle trunk-line leading from the pilot 120 of the exchange-section with which the calling subscriber is connected, to the exchange-section of the called subscriber, or, that the line of the called subscriber is busy. In either case, the calling subscriber will receive two rings, which, of course, will cause 125 him to wait, and after the expiration of a reasonable time, cause him to wind the sender-knob again for the purpose of sending another call for the same subscriber desired. 130

The ring-back mechanism used when either no trunk-line is available or when the called subscriber's line is busy, is illustrated in Fig. 48, and is identical in construction 5 in the pilot as well as in the terminator.

This ring-back mechanism consists of a normally rotating shaft 439, upon which are frictionally secured a number of ratchet-disks 440, separated by suitable sleeves and 10 each provided with four pins 441. The teeth of the ratchet 440 act upon movable springs of the ring-back contacts 96 and the disks are prevented from rotation by a 15 detent 442, forming one arm of the bell-crank 443, which is held at its longer end by a detent 444, forming the armature of the ring-back magnet 415 (205). The hubs of the 20 detents or levers 443 and 444 are connected by means of a helical spring 445. The operation of the apparatus is as follows:—

The magnet 415 (205) becomes energized, 25 attracts its armature and releases the lever 443, which, as the disk 440 is now taken along by the constantly rotating shaft 439, will be lifted by one of the pins 441, and the two teeth of the ratchet 440 between two pins will in succession press upon the 30 movable springs of the ring-back contacts 96, thereby throwing the magneto-generator twice on the line. As the energization of the magnets 415 (205) takes place only for a very short period of time, the lever 443 will, when leaving the pin 441 by which it was lifted, immediately return to its 35 normal position under the action of the spring 445 and will again be held by the detent 444, so that when the next pin strikes against the short lever 442, further rotation of the disk 440 will be prevented.

40 The circuit over which alternating current is sent for the purpose of ringing the bell of the calling subscriber is as follows:—

From the upper brush of the magneto-generator 446, Fig. 5 and Fig. 19, to the 45 lower spring of the upper group of ring-back-contacts 96, the movable spring forced in contact therewith by one of the teeth of the ratchet 440, the wire joint 95, the armature 93 of the clearing-out control-relay 94, the contact-point 92 now in contact therewith, the wire joint 91, the contact-spring 90 at the originator, Fig. 4, the upper shuttle-ribbon 89, the upper contact-brush 125 of the originator-shuttle 81, the upper terminal of the line-terminals 82 at the originator, the wire joint 88, over line B of the subscriber's instrument, the wire joints 240, 50 239, the bell 435, the condenser 436, the wire joint 234, the instrument-terminal 233, the contact-spring 24, the contact lever 21, the contact-spring 25, the wire joints 36, 37, 38, the sender-terminal 39, over line A to the 55 originator of the exchange-section, the wire joints 40, 110, the middle terminal of the line-terminals 82 at the originator of the

exchange-section with which the calling subscriber is connected, the middle terminal-brush 111 of the originator-shuttle 81, the lower shuttle-ribbon 112, the contact-spring 113, the movable spring of the lower groups 70 of ring-back-contacts 96, the lower spring thereof and now in contact therewith, to the lower brush of the magneto-generator 446.

It may be stated, that since a number-signal identifying the called subscriber in his 75 exchange-section has not yet been sent to the selectors at the terminator of this exchange-section, it will become necessary to release the sender and restore the same to its normal condition by energizing the sender-magnet. 80 It will be seen in Figs. 1 and 19 that the sender-magnet 32 is in shunt with the circuit just described, between the wire joints 38 and 240. This magnet acts upon a very 85 sensitive armature, and although alternating current is sent over the circuit, it will attract its armature and release the clock-work of the sender, causing it to complete the second half of the revolution. The impulses sent thereby are, of course, of no practical effect 90 or usefulness.

The busy ring-back mechanism of the terminator is of the same construction as the one in the pilot, and its operation is practically the same. When the magnet 205 at 95 the terminator becomes energized and attracts its armature, this ring-back mechanism is released, operates mechanically upon the ring-back contacts 168, and alternating current is sent from the magneto-generator 100 434 to the bell 435 of the calling subscriber in substantially the same way as hereinbefore described. It is obvious, of course, that according to the construction of the busy-ring-back mechanism, the bell will ring twice, 105 notifying thereby the calling subscriber that connection cannot be made with the subscriber desired. (See Fig. 20).

Clearing-out mechanism

110

The clearing-out mechanism in the present invention has the purpose of restoring all the parts used in establishing connection between the calling and the called subscriber to normal position, whether the call was successful or not. The two conditions which may be met which necessitate the clearing-out of the apparatus, are, first, when a successful call has been made and the called or the calling subscriber hang up their receivers. In this case, beginning with the originator shuttles, all shuttles will be brought back to their normal position of rest. In the second case, when a "busy" call was made, it will also become necessary to 115 clear out the apparatus and either only the originator-shuttle brought into operation extending the line from the calling subscriber to the pilot of the exchange-section with which he is connected, without finding an 120 125 130

idle trunk-line leading to the terminator of the exchange-section with which the called subscriber is connected, or, both the originator- and the pilot-shuttle, when an extension 5 of the line was successful to the terminator of the exchange-section with which the called subscriber is connected, but the line of the called subscriber was busy.

As stated hereinbefore, when the called 10 subscriber takes off his receiver, he throws battery on the line and energizes the magnets 228. By doing so, the bell-crank 242 is attracted by the magnet 228 and its short arm 431 holds the pin 427 as well as one of the 15 teeth of the ratchet 423. The pin 426 will then be in position immediately above the clearing-out contacts 430. When now, by hanging up the receiver, the magnet 228 becomes de-energized and releases the bell- 20 crank 242, the disks 423, 424 will be allowed to continue their rotation, the pin 426 will close the contacts 430 and thereby establish the following circuit:—

From ground 447, Figs. 6 and 24, to the 25 stationary spring of the contacts 430, the movable spring now in contact therewith, the clearing-out magnet 314 of the terminator, the wire joints 154, 153, 109, 51, 52, 53, 54, through the battery 55, the wire joint 56, 30 to ground 57.

The effect of current passing over this circuit just described is, to energize the magnet 314, which in attracting its armature releases the ratchet of the upper shuttle-tension of 35 the terminator, whereby the terminator-shuttle 225, under the superior force of the lower shuttle tension returns to its normal position. By the hanging-up of his receiver, and the de-energization of the magnet 228, and the called subscriber has also de-energized 40 the relay 396, which releases its armature 399 and breaks contact with the contact-point 400, thereby taking off battery from a circuit heretofore described, which contains the 45 clearing-out magnet 393 at the originator, Fig. 4 of the drawings. This magnet, in releasing its armature 419 allows the same to be pressed down by a pin, similar to the pin 426 in Fig. 46, which causes the armature 419 to close the clearing-out contacts 448, which, in turn, cause the clearing-out contacts 448 to close the following circuit:—

From ground 366, Figs. 4, 5 and 25 of the drawings, the wire joint 378, the contact-point 449, the contact-spring 448, the clearing-out magnet 313 of the pilot, the clearing-out magnet 312 of the originator, the wire joints 53, 54, through battery 55, the wire joint 56, to ground 57.

60 The effect of current passing over this circuit is to simultaneously energize the clearing-out magnets 312 of the originator and 65 313 of the pilot, which, in attracting their respective armatures, release the upper shuttle-tensions of the originator and the pilot,

whereby the originator-shuttle 81 and the pilot-shuttle 99 are brought back to their normal position under the superior strength of the lower shuttle-tension.

In a busy-call it is obvious, of course, that 70 the magnet 393 cannot be energized, because the circuit cannot be closed between the armature 399 and the contact-point 400, and, therefore, the pin of the clearing-out device 420 will, after making a full revolution, act 75 upon the armature 419 and press the same against the clearing-out contact 448, closing a circuit over the contact 449, and energizing the clearing-out magnets 312 in the originator and 313 in the pilot, restoring the 80 respective shuttles 81 and 99 to their normal position.

The restoration of the originator shuttle 81, when no idle trunk-line can be found in the pilot to which the pilot-shuttle 99 can 85 make connection, will be brought about in a similar way, as stated hereinbefore, since the clearing-out magnet 393 will not be able to receive current, and, therefore, the pin of the clearing-out device 420 will, after 90 completing a full revolution, act upon the armature 419, force the same against the clearing-out contact 448 and close circuit over the contact-point 449, resulting in the 95 energization of the clearing-out magnet 312 of the originator which, in attracting its armature, releases the upper shuttle-tension of the originator, whereby the originator shuttle 81 is restored to normal position, as 100 hereinbefore stated.

It now remains to be shown how the thousand-and-hundred-selectors in the pilot and the ten- and unit-selectors in the terminator of an exchange-section are restored to 105 normal position after having received their proper number of selective impulses.

The restoration of any of the selectors, as will be remembered from the mechanical description of the selectors, is necessary under all conditions, when selective impulses have 110 been received by the selectors, but will be brought about by two different devices, i. e., in the first case, when the signal received has resulted in the displacement of a shuttle during a successful call or a partially successful call, or, in the second case, when the signal received by the selector has not resulted in the displacement of a shuttle. In the first case, the restoration is brought about by a device provided at the clutch mechanism 304' of the pilot and the terminator, and in the second case, it is brought about by a device provided at the ring-back mechanism, illustrated in Fig. 48.

The clutch-mechanism 304' has on its periphery an insulating piece 450 which, in the normal position of the clutch mechanism, is in contact with a contact-spring 451, but which contact-spring during the operation 120 or revolution of the clutch-mechanism 304', 125

makes contact with the metallic parts thereof and closes a circuit as follows:—

From ground 452, to the clutch-mechanism 304', the contact-spring 451, the wire joints 453, 454, to the make-and-break wheel 353 of the selector. It will be seen from Fig. 52 that this make-and-break wheel has its teeth spaced like the contacts, with the tooth corresponding to the zero-contact-point left out.

During the operation of the selector, a contact-spring 361 makes contact with the teeth of the make-and-break wheel 353, as described hereinafter, with the exception of the normal position, where, on account of the lack of a tooth, this spring 361 cannot make contact with the make-and-break-wheel 353. In consequence thereof, after the selective impulses are received by the selector, current will pass from the ground over the circuit just described, to the make-and-break wheel 353, which in making contact with the contact-spring 361 will send impulses through the selector-magnets and cause the trailer-brush 139 to continue its rotation and complete a full revolution until no further impulse can be sent over the contact-spring 361 which, thereby, will cause the make-and-break wheel to remain in its normal position of rest.

The circuit from the contact-spring 361 is continued to wire joint 103, the selector-magnet 104 or any one of the other selector-magnets, which magnets in becoming energized, cause the rotation of the trailer-brush 139, the circuit then continuing to wire joints 105, 106, 107, 108, 109, 51, 52, 53, 54, through battery 55, the wire joint 56, to ground 57. The selector-magnets 104, 119 and 161, 181, respectively, are in shunt, the energization of the same for the purpose of restoring the selectors, therefore, takes place simultaneously.

In case of a not successful call, the energization of the selector-magnets takes place over the ring-back device, illustrated in Figs. 48 and 22, in which an insulating piece 455 is provided on the periphery of the ring-back device, which normally is in contact with a contact-spring 456. During the operation of the ring-back device brought about by a non-successful call or busy call, the contact-spring 456 will make contact with the metallic parts of the ring-back device, and a circuit will be closed as follows:—

From ground 457 to the ring-back device, the contact-spring 456, Fig. 5 and Fig. 22, the wire joints 453, 454, the make-and-break wheels 353, the contact-spring 361, the selector-magnets 104, 119, the wire joints 105, 106, 107, 108, 109, 51, 52, 53, 54, through battery 55, the wire joint 56, to ground 57.

The energization of the selector-magnets

will again result in the step-by-step movement of the trailer-brush of the selectors, completing a full revolution, until the make-and-break wheel 353 is brought into zero-position and the contact-spring 361 cannot make contact therewith.

The restoration of the ten- and unit-selector in the terminator of an exchange-section takes place in a similar way by means of the ring-back device of the terminator and by closing a circuit from ground 458 over the ring-back mechanism, the contact-spring 460, through the make-and-break wheels of the selectors to battery and ground, as heretofore described and shown in Fig. 23.

It has been found in the operation of telephone-exchanges that often trouble arises which necessitates the calling up of the trouble-man at the telephone-exchange for the purpose of having defects in the apparatus or in the line repaired. In the present invention there is a device provided at the sender of a subscriber which sends a signal "0000" to the exchange, by which the trouble-man at the exchange is identified.

This device consists of an emergency-button or contact 361, Fig. 1 of the drawings. It contains three springs which may be brought in contact with each other by pressing the button in case the sender should fail to send a signal, or no answer should be received from the exchange when the signal has been sent and a reasonable time expired.

The upper contact-spring of this emergency-contact 361 is connected to ground, the middle contact-spring to line B and the lower contact-spring to line A. It is clear that when ground 29 is placed on the sender and held thereon for some time, the first effect of this ground will be exactly the same, as the effect brought about by turning the winding-knob 30 and releasing it to its normal position, whereby contact lever 21 makes contact with contact-springs 22, 23 and places ground 29 on the line. As hereinbefore stated, the effect of this current is to operate the allotter, Figs. 2 and 3, and cause the originator-shuttle to make contact with the line-terminals of the calling subscriber at the originator. Since now the emergency-contact 361 is still held pressed together, a circuit will be closed over lines A and B and the originator-shuttle, to the thousand- and hundred-selectors of the pilot which will receive the signal "00" and cause the pilot-shuttle to make contact with the trunk line "00", extending thereby the line of the calling subscriber to the terminator of the "00" exchange-section.

Since the emergency-button is still held, an impulse will also be sent to this terminator as soon as the pilot-shuttle makes contact with the "00" trunk-line-terminal, resulting in the operation of the ten- and unit-

selectors at the terminator of the "00" exchange-section, sending one impulse through each of the same and causing the terminator-shuttle to make contact with the "00" subscriber in the "00" exchange-section, i. e., with the trouble-man, with whom conversation may now be held as to the trouble experienced.

One of the most important points of the present invention arising from the fact that the subscriber's sender is normally off-ground, and ground is placed thereon by means of the returning winding-knob or the emergency-button, is, that whenever ground is placed on the sender and held thereon for a considerable time, it will result in sending the signal "0000" to the exchange and since, as stated before, the trouble-man of the exchange is always identified by the call-number "0000", the subscriber's sender automatically causes connection between a calling subscriber and the trouble-man, which will enable the subscriber to inform the latter of any difficulty which he may find in the operation of the machine.

As new and useful is considered and desired to be protected by United States Letter Patent—

1. A telephone exchange system comprising groups of subscribers' lines, a lesser group of primary link circuits for each of said groups, other link circuits each adapted for connection with primary link circuits in a plurality of groups, means for associating calling lines with the primary link circuits of their related groups, automatic means for effecting simultaneously initiated selection of idle ones of said other link circuits, means for connecting the so-selected link circuits with primary link circuits in a plurality of groups, and means for extending the selected link circuits to connection with wanted lines.

2. A telephone exchange system comprising groups of subscribers' lines, a lesser group of primary link circuits for each of said groups, other link circuits each adapted for connection with primary link circuits in a plurality of groups, means for associating calling lines with the primary link circuits of their related groups, automatic means for connecting said primary link circuits with idle ones of said other link circuits, an automatic switching mechanism associated with each of said other link circuits to connect with wanted lines, and controlling means adapted to simultaneously initiate actuation of a plurality of said mechanisms to connect a plurality of said other link circuits with a plurality of wanted lines.

3. A telephone exchange system comprising groups of subscribers' lines, a lesser group of primary link circuits for each of said groups, other link circuits each adapted

for connection with primary link circuits in a plurality of groups, means for associating calling lines with the primary link circuits of their related groups, selective mechanism automatically actuated to connect said primary link circuits with idle ones of said other link circuits, means for initiating actuation of the selective mechanism to connect primary link circuits of any one group independently of the time of initiating actuation of the selective mechanism to connect primary link circuits of other groups, and means for extending said other link circuits to connection with wanted lines.

4. A self-acting telephone-exchange divided into exchange-sections, each exchange-section comprising more than two sub-sections, stationary and movable terminals at each sub-section, loop circuits of which said movable terminals form the terminal connectors, means at each exchange-section and under the control of the calling subscriber for selecting stationary terminals with which connection is desired, and means at each exchange-section for selecting movable terminals to be used in making these connections.

5. A self-acting telephone-exchange divided into exchange-sections, each exchange-section comprising more than two sub-sections, stationary and movable terminals at each sub-section, loop circuits of which said movable terminals form the terminal connectors, automatic means at each exchange-section and under the control of the calling subscriber for selecting stationary terminals with which connection is desired, and automatic means at each exchange-section for selecting movable terminals to be used in making these connections.

6. A self-acting telephone-exchange divided into exchange-sections, each exchange-section consisting of sub-sections, stationary and movable terminals at each sub-section, loop circuits of which said movable terminals form the terminal connectors, means, within the control of subscribers, at each exchange-section, for selecting stationary terminals with which connection is desired, and means, beyond the control of subscribers, at each exchange-section, for selecting movable terminals to be used in making these connections.

7. A self-acting telephone-exchange divided into exchange-sections, each exchange-section consisting of sub-sections, stationary and movable terminals at each sub-section, loop circuits of which said movable terminals form the terminal connectors, automatic means, within the control of subscribers, at each exchange-section, for selecting stationary terminals with which connection is desired, and automatic means, beyond the con-

trol of subscribers, at each exchange-section, for selecting movable terminals to be used in making these connections.

8. A telephone exchange system comprising subscribers' lines, a plurality of trunk circuits available for connection to a wanted line, automatic selecting mechanism for extending the circuit of a calling line to an idle trunk circuit, and means for sending a characteristic signal over the calling line in case all of the trunk circuits available for connection to said wanted line are in use.

9. A telephone exchange system comprising subscribers' lines, plural groups of trunk circuits available for connection to wanted lines, automatic selecting mechanism for extending the circuit of a calling line to an idle trunk circuit in an elected one of said groups, means for determining the busy or idle condition of the individual trunk circuits of the elected group, and means for sending a characteristic signal over the calling line in case all of the link circuits in an elected group are busy.

10. A self-acting telephone-exchange divided into exchange sections to each of which a group of subscribers is connected and each of which consists of sub-sections, stationary terminals for the exclusive use of calling subscribers at one sub-section, stationary terminals for the exclusive use of called subscribers at another sub-section, stationary terminals at an intermediate sub-section, movable terminals at each of the sub-sections for connection with the stationary terminals, means for selecting the stationary terminals with which connection is desired, and means for selecting the movable terminals to be used in making these connections.

11. A system of electrical communication comprising subscribers' stations and a self-acting exchange divided into exchange sections to each of which a group of subscribers is connected and each of which consists of sub-sections, signal-sending means at the subscribers' stations adapted to send simultaneously more than one variable signal, forming a group, and to send successively groups forming an entire signal, signal-receiving means at each exchange-section and automatically operated means, controlled by said signal-receiving means, for connecting any idle pair of subscribers through the exchange.

12. The combination with a plurality of displaceable members or shuttles, of a lifting device normally out of engagement with said shuttles adapted to engage any one of the shuttles to lift the same, and controlling means for the lifting device to cause the disengagement of the same at a predetermined position.

13. The combination with a plurality of displaceable members or shuttles, of a lift-

ing device normally out of engagement with said shuttles adapted to engage any one of the shuttles to lift the same, and a plurality of controlling means for the lifting device adapted to cause the dis-engagement of the latter from the shuttles at a predetermined position.

14. The combination with a plurality of displaceable members or shuttles, of a lifting device adapted to engage any one of the shuttles, of controlling means for the lifting device comprising a plurality of rotating cylinders, and of helically arranged stops thereon, said cylinders adapted to cause the disengagement of the lifting device from the shuttles at a predetermined position of the cylinders.

15. The combination with a plurality of displaceable members or shuttles, of a lifting device adapted to engage any one of the shuttles, a set of normally rotating cylinders, of helically arranged stops on said cylinders, a pawl for each stop and adapted to engage the same for stopping the rotation of said cylinder, a second set of cylinders driven by said first set of cylinders, and helically arranged stops on each of said second set of cylinders and adapted to cause the disengagement of the lifting device from the said shuttles at a predetermined position of the cylinders.

16. The combination with a normally rotating cylinder, of helically arranged stops on said cylinder, a pawl for each stop and adapted to engage the same for stopping the rotation of said cylinder, and electro-magnetic means for causing the operation of said pawl.

17. The combination with a normally rotating cylinder, of a series of helically arranged stops on said cylinder, of means for each stop adapted to interrupt the rotation of said cylinder at a predetermined position, and of electro-magnetic controlling means for each of said interrupting means.

18. The combination with a plurality of displaceable members or shuttles, of a plurality of line-terminals, of a common lifting means for said shuttles, and of a controlling means for said lifting means adapted to disengage said shuttles from said lifting means and cause contact of the same with any one of the line terminals.

19. The combination comprising a contact-member, an operating means for said contact-member, an actuating member having a lifting tooth and carrying said operating means, and a holding means for said actuating member and adapted to release the same for the purpose of placing the lifting tooth in the operative position.

20. The combination with a displaceable member or shuttle comprising a contact lever and an actuating lever, of a lifting tooth on said actuating member, of a lifting de-

vice for said shuttle and adapted to engage said lifting tooth, of means for causing said lifting device to disengage from said lifting tooth at a predetermined position of said shuttle, and of means on said lifting device adapted to engage said actuating lever and to cause the operation of said contact lever.

21. The combination with a plurality of displaceable members or shuttles, of a lifting device adapted to engage any of said shuttles, of an actuating lever on each shuttle and having a lifting tooth, of a detent normally holding the lifting tooth of the actuating lever out of the path of the lifting device, and operating means for said detent to cause the release of said actuating member so as to place the lifting tooth into the path of the lifting device.

22. The combination with a normally rotating cylinder, of helically arranged stops on said cylinder, of means adapted to engage any one of said stops, and of means for resetting said engaging means.

23. The combination with a normally rotating shaft, of a second shaft adapted to be frictionally driven by said first shaft, an escapement wheel on said second shaft, a verge engaging said escapement wheel, electromagnetic means adapted to operate said verge, a unidirectionally rotating contact-brush, and a series of stationary contact points with which said contact-brush is adapted to make contact according to the number of impulses received by said electromagnetic means.

24. In a self-acting telephone-exchange, the combination with means for sending an electrical signal consisting of groups or sets of separate variable signals, of a power-operated signal-sender, and means independent of said signal-sender, for causing the sending of a signal of a predetermined character when the power-operated signal-sender should refuse to operate.

25. A telephone exchange divided into sections, trunk lines to connect said sections, automatic switching means to connect subscribers through said trunk lines, signal receiving means at said exchange to control said switching means, the operation of said switching means and the said signal receiving means being non-simultaneous.

26. A telephone exchange divided into sections, trunk lines to connect said sections, automatic switching mechanism to connect subscribers through said trunk lines, signal receiving mechanism at said exchange to control said switching mechanism, and a signal sender at each subscriber's station to control the operation of the signal receiving mechanism at the exchange without operating the said switching mechanism.

27. A telephone exchange divided into sections, trunk lines to connect said sections, automatic switching means local to the ex-

change to connect subscribers' lines through said trunk lines, signal receiving means to control the operation of said switching means, signal sending means at the subscribers' stations for controlling said signal receiving means without operating said switching means, the operation of said signal receiving means alternating with the operation of said switch mechanism to effect connection between subscribers.

28. A telephone exchange system comprising groups of calling lines, a group of trunk lines, a plurality of subscribers' lines related to said trunk lines, substation transmitters for said lines, other trunk lines for connecting any trunk line of said group with a calling line in any of said groups, a central source of talking current, transmitter current supply connections individual to the talking conductors of said first mentioned trunk lines, and automatic switching mechanism for connecting said first mentioned trunk lines individually with wanted lines of said plurality, whereby the transmitters of said wanted lines are energized and conversational circuits completed extending from calling lines in any of said groups.

29. A telephone exchange system comprising groups of subscribers' lines, groups of trunk lines, a plurality of subscribers' lines related to each group of trunk lines, substation transmitters for said lines, other trunk lines for connecting any trunk line of said groups with calling lines in a plurality of said groups of lines, a central source of talking current, transmitter current supply connections individual to the talking conductors of said groups of trunk lines, and automatic switching mechanism for connecting the trunk lines of said groups individually with wanted lines of said related pluralities, whereby the transmitters of said wanted lines are energized and conversational circuits completed extending from calling lines in any of said groups.

30. A telephone exchange system comprising a temporarily established talking connection including a plurality of link circuits, controlling-magnet bridges for said link circuits temporarily cut off from said connection, a battery bridge maintained across said circuit for supplying talking current, and restoring means for said link circuits controlled by said battery bridge.

31. A telephone exchange system comprising a talking connection including a plurality of link circuits, a plurality of controlling-magnet bridges on said circuits, automatic means for reducing the number of bridges during talking, automatic releasing means for disconnecting between subscribers, and a bridge maintained on said connection during conversation to control said releasing means.

32. A telephone exchange system compris-

- ing subscribers' lines, automatic means including a plurality of serially related trunk lines for trunking a calling line into connection with a called line to form a talking circuit, pairs of controlling magnets in bridge of said trunk lines, and automatic means for disconnecting certain of said magnets prior to conversation over said talking circuit.
- 10 33. A telephone exchange system comprising subscribers' lines, link circuits, traveling talking contacts for extending said link circuits toward wanted lines, automatic switching mechanism for advancing said contacts, a variable contact device for controlling said mechanism, and a circuit including one or more of said talking contacts for controlling said contact device.
34. A telephone exchange system comprising subscribers' lines, link circuits, traveling talking contacts for extending said link circuits toward wanted lines, automatic switching mechanism for advancing said contacts, a variable contact device for controlling said mechanism and a circuit including one or more of said talking contacts to determine the rate of operation of said contact device.
35. A telephone exchange system comprising subscribers' lines, link circuits, traveling talking contacts for extending said link circuits toward wanted lines, automatic switching mechanism for advancing said contacts, variable contact means for controlling said mechanism, driving means for said contact means and a circuit including one or more of said talking contacts for controlling said driving means.
- 40 36. A telephone exchange system comprising subscribers' lines, a link circuit, traveling talking contacts for extending said link circuit toward wanted lines, a switching mechanism for automatically advancing said contacts, a variable contact device for controlling said mechanism temporarily associated therewith, driving means for said device and a circuit including one or more of said talking contacts for controlling said driving means.
- 45 37. A telephone exchange system comprising subscribers' lines, link circuits, traveling talking contacts for extending said link circuits toward wanted lines, automatic switching mechanism for advancing said contacts, variable contact means for controlling said mechanism, driving means for said contact means, arresting means for said driving means and a circuit including one or more of said talking contacts for controlling said arresting means.
- 50 38. A telephone exchange system comprising subscribers' lines, a link circuit, traveling talking contacts for extending said link circuit toward wanted lines, a switching mechanism for automatically advancing said
- 55 contacts, a variable contact device for controlling said mechanism temporarily associated therewith, arresting means for said device and a circuit including one or more of said talking contacts for controlling said arresting means.
- 60 39. A telephone exchange system comprising link circuits adapted for sequential relation in building up a talking circuit between two subscribers' lines, a traveling contact terminal for each of said link circuits, groups of waiting contacts for each of said contact terminals, automatic switching mechanism including means primarily adjusted for advancing a contact terminal to an elected group of waiting contacts and secondarily adjusted for advancing said terminal to engagement with a contact in the elected group, and a local controlling circuit for said mechanism including serially related contact terminals of a plurality of said link circuits.
- 65 40. A telephone exchange system comprising subscribers' lines, a link circuit connected with a calling line, traveling contacts constituting terminals of said link circuit, groups of waiting contacts co-operating with said traveling contacts, automatic mechanism primarily controlled for advancing said traveling contacts to an elected group of waiting contacts and secondarily controlled for advancing said traveling contacts to engagement with contacts in the elected group, a controlling circuit for said mechanism, and a switch actuated responsive to initial movement of said traveling contacts to alter said controlling circuit.
- 70 41. A telephone exchange system comprising a plurality of telephone circuits, a plurality of waiting contacts constituting terminals of said circuits, a co-operating traveling contact, controlling means to variably determine the advance of said traveling contact, electro-magnetic means for adjusting said controlling means to position corresponding with the waiting contact of any one of said circuits, and means for advancing said traveling contact to engage that waiting contact determined by the adjustment of said controlling means.
- 75 42. A telephone exchange system comprising a plurality of subscriber's lines, a plurality of waiting contacts constituting terminals of said lines, a co-operating traveling contact, controlling means to variably determine the advance of said traveling contact, electro-magnetic means for adjusting said controlling means to position corresponding with the waiting contact of a predetermined line, and means for advancing said traveling contact to engage that waiting contact determined by the adjustment of said controlling means.
- 80 43. A telephone exchange system comprising a plurality of trunk lines, a plurality of

waiting contacts constituting terminals of said trunk lines, a co-operating traveling contact, controlling means to variably determine the advance of said traveling contact, electro-magnetic means for adjusting said controlling means to position corresponding with the waiting contact of an idle trunk line, and means for advancing said traveling contact to engage that waiting contact determined by the adjustment of said controlling means.

44. A telephone exchange system comprising groups of telephone circuits, groups of waiting contacts constituting terminals of

15 said circuits, a co-operating traveling contact, controlling means to variably determine the advance of said traveling contact, electro-magnetic means for adjusting said controlling means to position corresponding 20 with the group and waiting contact of any one of said circuits, and means for advancing said traveling contact to that group and to engagement with that waiting contact determined by the adjustment of said controlling 25 means.

45. A telephone exchange system comprising groups of telephone circuits, groups of waiting contacts constituting terminals of said circuits, a co-operating traveling contact, controlling means to variably determine the advance of said traveling contact, electro-magnetic means for adjusting said controlling means to position corresponding with any one of said groups of contacts, 35 and means for advancing said traveling contact to that group determined by the adjustment of said controlling means.

46. A telephone exchange system comprising groups of telephone circuits, groups of 40 waiting contacts constituting terminals of said circuits, a co-operating traveling contact, controlling means to variably determine the advance of said traveling contact, electro-magnetic means for adjusting said 45 controlling means to position corresponding with any one of said groups of circuits, and means for advancing said traveling contact to that group determined by the adjustment of said controlling means and to engagement 50 with the waiting contact of a circuit in said group.

47. A telephone exchange system comprising groups of subscribers' lines, groups of waiting contacts constituting terminals of 55 said lines, a co-operating traveling contact, controlling means to variably determine the advance of said traveling contact, electro-magnetic means for adjusting said controlling means to position corresponding with any one of said groups of lines, and means 60 for advancing said traveling contact to that group determined by the adjustment of said controlling means and to engagement with the waiting contact of a predetermined line in said group.

48. A telephone exchange system comprising groups of trunk lines, groups of waiting contacts constituting terminals of said lines, a co-operating traveling contact, controlling means to variably determine the 70 advance of said traveling contact, electro-magnetic means for adjusting said controlling means to position corresponding with any one of said groups of trunk lines, and means for advancing said traveling contact 75 to that group determined by the adjustment of said controlling means and to engagement with the waiting contact of an idle trunk line in said group.

49. A telephone exchange system comprising groups of telephone circuits, waiting contacts in rectilinear relation constituting terminals of said circuits and arranged in corresponding groups, a co-operating traveling contact adapted for rectilinear adjustment to relation with any one of said waiting contacts, controlling means for each of said circuits, means for giving characteristic condition to said controlling means, and means for automatically adjusting said 90 traveling contact to the group and to engagement with the contact of any one of said circuits having its controlling means in said characteristic condition.

50. A telephone exchange system comprising groups of telephone circuits, waiting contacts constituting terminals of said circuits arranged in corresponding groups having rectilinear relation, a co-operating traveling contact adapted for rectilinear adjustment to relation with any one of said waiting contacts, controlling means for each of said groups of circuits, means for giving characteristic condition to said controlling means, and means for automatically advancing said traveling contact to relation with the group of waiting contacts of a group of said circuits having its controlling means in said characteristic condition.

51. A telephone exchange system comprising groups of telephone circuits, waiting contacts constituting terminals of said circuits arranged in corresponding groups having rectilinear relation, a co-operating traveling contact adapted for adjustment by rectilinear motion to relation with any one of said waiting contacts, controlling means for each of said circuits, means for giving characteristic condition to said controlling means, and means for advancing said traveling contact to the waiting contacts of a group of said circuits and automatically to engagement with the waiting contact of a circuit of said group having its controlling means in said characteristic condition.

52. A telephone exchange system comprising groups of trunk lines, groups of waiting contacts in rectilinear relation constituting terminals of said trunk lines, a co-operating traveling contact adapted for 130

adjustment by rectilinear motion to relation with any one of said waiting contacts, means for advancing said traveling contact to the group of waiting contacts of an elected group of trunk lines and automatically to engagement with the waiting contact of an idle trunk line of said elected group.

53. An automatic switching mechanism comprising a plurality of waiting contacts, a co-operating traveling contact, means for advancing said traveling contact, an engaging member to limit the advance of said traveling contact, and means for variably adjusting said engaging member to position corresponding with any of said waiting contacts.

54. An automatic switching mechanism comprising a longitudinally disposed plurality of waiting contacts, a co-operating longitudinally movable traveling contact, means for advancing said traveling contact, an engaging member to limit the advance of said traveling contact, and means for variably adjusting said engaging member prior to the advance of said traveling contact.

55. An automatic switching mechanism comprising a longitudinally disposed plurality of waiting contacts, a co-operating longitudinally movable traveling contact, an engaging member to limit the extent of movement of said traveling contact, means for variably positioning said engaging member, and means for advancing said traveling contact to the limit established by the position of said engaging member.

56. An automatic switching mechanism comprising a longitudinally disposed plurality of waiting contacts, a co-operating longitudinally movable traveling contact, a plurality of engaging members to limit the advance of said traveling contact, means for variably positioning said engaging members, and means for advancing said traveling contact to the limit established by the position of said engaging members.

57. An automatic switching mechanism comprising a plurality of waiting contacts, a co-operating traveling contact, a plurality of engaging members to variably limit the advance of said traveling contact, means for adjusting said engaging members, and means for subsequently advancing said traveling contact to the limit established by the adjustment of said engaging members.

58. A selector comprising a movable switch member, stop setting mechanism, an electro-magnetic step-by-step device, responsive to selecting impulses, for adjusting said stop setting mechanism, a source of motive power, means for applying the same to advance said switch member, and means controlled by said stop-setting mechanism according to its completed selective adjust-

ment, for cutting off the application of motive power from said switch member.

59. In a selector, the combination with a movable switch member, of a continuously acting source of power for advancing the same, a device controlling the application of power to drive said switch member, a controller mechanism having a relatively movable part arranged to travel proportionately to the advance of the switch member, means for selectively adjusting said controller mechanism, and means controlled by said relatively movable part in reaching a point in its travel predetermined by the adjustment of said controller mechanism, for releasing said device.

60. A selector switch comprising stationary line terminals, a movable carrier and contact brushes carried thereby for traveling over and making contact with said line terminals, stop-setting mechanism, step-by-step mechanism arranged to adjust said stop-setting mechanism for long steps, other step-by-step mechanism arranged to adjust said stop setting mechanism for short steps, electro-magnetic means responsive to selective current impulses, for actuating said step-by-step mechanisms, and means for moving said carrier in a single direct advance over the distance predetermined by the completed selective adjustment of said stop-setting mechanism.

61. A selector switch comprising a movable brush carrier, a magnet adapted to respond to selecting impulses, step-by-step mechanism actuated by said magnet, a stop arranged to be set by said step-by-step mechanism in its advance to determine the travel of said brush-carrier, motor mechanism, a device for coupling said motor mechanism to said brush-carrier to move the latter directly to the predetermined point, and means controlled by said stop for throwing off said device.

62. In a selector switch controlling device, the combination with a plurality of relatively adjustable controller members, of a part having relative movement with respect to said controller members, and stop means brought into action by the mechanical co-operation of said relatively-movable part with said controller members jointly, according to their adjustment.

63. In a selector switch controlling mechanism the combination with a plurality of relatively adjustable controller parts, of selectively operated step-by-step mechanism for imparting such relative adjustment, and stop means controlled by the relative adjustment of said parts.

64. A selector switch controlling mechanism comprising relatively adjustable parts adapted to act in combination, electromagnetic selective mechanism for setting said

controller parts in definite combination, a stop means, and means responsive to the combination of controller parts for actuating said stop means.

5 65. A selector switch controlling mechanism comprising relatively-adjustable stop-setting parts, a stop device, and means adapted to co-operate with said stop-setting parts jointly to actuate said stop device.

10 66. A selector switch controlling mechanism comprising a stop, a plurality of stop setting parts, electromagnetic means for causing the relative adjustment of said stop setting parts, and means whereby the relative position of said stop setting parts determines the operative position of said stop.

15 67. In a telephone system, the combination of a plurality of trunk-lines, and a trunk-selecting switch mechanism therefor,

20 68. In a telephone system, the combination of a plurality of trunk-lines, a trunk-selecting switch mechanism comprising mechanical devices for mechanically and automatically selecting the first idle trunk-line next in order after the one last put in use.

25 69. In a telephone system, the combination of a plurality of trunk-lines, a trunk-selecting switch mechanism under the control of the subscribers and adapted for selectively and successively appropriating the different trunk-lines for use, and adapted to skip any trunk-lines which are busy, and a busy-release mechanism or means adapted for use by any subscriber for effecting a disconnection when all of the trunk-lines are busy.

35 70. In a telephone system, the combination of a plurality of trunk-lines, a trunk-selecting switch mechanism therefor, and a busy mechanism for automatically giving a calling subscriber the busy signal if all of the trunk-lines are in use.

40 71. In a telephone system, the combination of a plurality of trunk-lines, a trunk-selecting switch mechanism under the control of the subscribers and adapted for selectively and successively appropriating the different trunk-lines for use, and adapted to skip any trunk-lines which are busy, a busy-release mechanism or means adapted for use by any subscriber for effecting a disconnection when all of the trunk-lines are busy, and release circuits for effecting a restoration of the apparatus.

45 72. In a telephone system, the combination of a plurality of trunk-lines, a trunk-selecting switch mechanism therefor, a busy mechanism for automatically giving a calling subscriber the busy signal if all of the trunk-lines are in use, and release circuits for effecting a restoration of the apparatus.

50 73. In a telephone system, a plurality of subscriber's lines, a plurality of trunk lines, a trunk selecting switch mechanism associated therewith, means for operating said mechanism to seize a trunk and connect a calling line therewith, said switching mecha-

nism comprising purely mechanical devices for automatically selecting the first idle trunk line next in order after the one seized by the calling line.

55 73. A telephone exchange system comprising subscriber's telephone lines, "selector" switches for extending the circuits of calling lines, a plurality of link-circuits connected to each "selector" switch and available for connection with a calling line, and means for sending a characteristic signal over the calling line in case all of the link-circuits available to said line are in use.

78. In a telephone exchange system, line circuits, automatic switching apparatus for interconnecting the same, actuating and release mechanism therefor, an auxiliary switch, actuating and restoring means therefor, and a circuit connection from said auxiliary switch to the releasing means of the associated connective automatic switching apparatus, whereby the act of restoring the auxiliary switch will clear out and restore its associated switching apparatus.

75. In a telephone exchange system, line circuits, link circuits and automatic switches, including a connector switch and link for interconnecting the lines, actuating and release magnets for said connector switch, an electromagnetically actuated switch auxiliary to the connector switch having its contacts connected with the circuit, but actuated independently of said connector, and a release circuit for the connector controlled in the movement of the contacts of said auxiliary switch.

76. In a telephone exchange system, a plurality of lines, means for rendering said lines busy, a plurality of selectively operable switching devices arranged to connect with said lines, a line testing means common to said devices, and means responsive to the operation of said testing means to actuate one of said devices to select and seize the wanted line.

77. In an automatic telephone system, a calling and a called subscriber's line, automatic switches for effecting interconnection between a calling and a called subscriber's line, a ringing generator, means only operative to connect it to the called line when said line is selected by one of said automatic switches, means acting periodically to actuate said connecting means, and means under the control of the called subscriber for disabling said connecting means, substantially as described.

78. In an automatic telephone system, the combination with a plurality of normally open instrument circuits, each provided with signalling devices, a connector switch mechanism serving to connect one, a calling circuit, with another a called circuit, and devices for operating said switch mechanism to select a desired called circuit, of a source

- of current supply for signalling purposes, a relay operated upon the cessation of operation of the switching devices to automatically apply said current to the selected called 5 instrument circuit, means for interrupting the flow of said current to cause alternating periods of activity and quiescence in the signaling device of the called circuit and a relay connected to said called circuit during 10 the quiescent periods which is adapted to be actuated when said instrument circuit is closed to remove the signaling current.
79. In an automatic telephone system, the combination with a plurality of normally 15 open sub-station instrument circuits, each provided with signaling devices, a connector switch mechanism at a main station serving to connect one, a calling circuit, with another a called circuit, and devices at the 20 main station for operating said switch mechanism to select a desired called sub-station circuit, of a central station source of current supply for signaling purpose comprising a circuit which is normally disconnected from the instrument circuits, a ringing switch at the main station, and main station self-acting means to operate said switch intermittently only upon the cessation of movement of the switching devices to intermittently connect the signaling circuit to the 25 called instrument circuit.
80. In an automatic telephone system, the combination with a plurality of normally open instrument circuits each provided with 30 signalling devices, a connector switch mechanism comprising terminals for said lines and having movable terminals co-operating therewith which serve to connect one, a calling circuit with another a called circuit, and mechanism for operating the movable terminals, of a source of current for signaling purposes comprising a circuit which is normally disconnected from the instrument circuit, and a signalling switch which is automatically intermittently operated and controls contacts which open the calling end of the line and connects the signalling circuit to the called end thereof following upon the 35 cessation of movements of the movable terminals.
81. In an automatic telephone system, the combination with a plurality of normally open instrument circuits each provided with signalling devices, a connector switch mechanism comprising stationary terminals for said lines and having movable terminals co-operating therewith which serve to connect one, a calling circuit with another a called circuit and mechanism for operating the movable terminals, of a source of current for signalling purposes comprising a circuit which is normally disconnected from the instrument circuit, and a signalling switch which is automatically intermittently operated and controls contacts which open the 40 calling end of the line and connects the signalling circuit to the called end thereof following upon the cessation of movements of the movable terminals.
82. In a telephone exchange system, a calling and a called subscriber's line, a link circuit having switch terminals for interconnecting them and an automatic connector switch mechanism operating in connection with said terminals, a ring switch intermittently actuated only when the connector switch mechanism has selected the terminals of a called line to connect a ringing generator with said called line, and means controlled by the called subscriber, for disabling said ringing switch when the call is answered, substantially as described.
83. A telephone system including a calling and a called line, a source of calling current, a relay controlling switch contacts operatively connected with said source, an electrically controlled selective switch adapted to connect with the called line, test means for said switch differently operative according to the busy or idle condition of the called line, means for applying said test means to a test contact of the called line on selection thereof, and a circuit for said relay under the control of said test means and operative thereby to actuate said relay to cause the inclusion of said source in circuit with the called line.
84. A telephone system including a calling and a called line, an electrically controlled selective mechanism adapted to connect with the called line, a source of alternating current, a switch individual to said mechanism adapted when actuated to include said source in circuit with the called line, actuating means for said switch, and means at the sub-station of the called line to discontinue the inclusion of said source in circuit with said called line.
85. A telephone system including a calling and a called line, an electrically controlled selective mechanism adapted to connect with the called line, a source of calling current, a switch adapted when actuated to include said source in circuit with the called line, intermittently operated actuating means for said switch, and means at the sub-station of the called line to discontinue the inclusion of said source in circuit with said called line.
86. A telephone system including a calling and a called line, an electrically controlled selective mechanism adapted to connect with the called line, a source of calling current, a switch adapted when actuated to include said source in circuit with the called line, actuating means for said switch, means at the sub-station of the called line to discontinue the

inclusion of said source in circuit with the called line, test means for said mechanism operative responsive to the idle condition of the called line to cause the operation of said actuating means, and means for applying said test means to a contact of the called line on selection thereof.

87. A telephone system including a calling and a wanted line circuit, an electrically controlled selective mechanism at the main station comprising line connecting conductors to connect a calling circuit with the wanted line circuit, a source of alternating calling current at the main station, a switch adapted when actuated to include said source in circuit intermittently with the wanted line circuit through a portion of said line connecting conductors, main station self-acting actuating means for said switch, means at the sub-station of the wanted line to discontinue the inclusion of said source in circuit with the wanted line circuit, test means for said mechanism operative responsive to the busy condition of the wanted line circuit to prevent the inclusion of said source in circuit with the wanted line circuit, and means for applying said test means to a contact of the wanted line circuit on selection thereof.

88. A telephone system including a plurality of telephone lines, an electrically controlled selective mechanism comprising a link circuit adapted to interchangeably connect any of said calling line with any desired wanted line, a source of alternating calling current, a switch adapted when actuated to include said source in circuit intermittently with the wanted line through conductors of said link circuit, actuating means for said switch, means at the sub-station of the wanted line to effect the discontinuance of the inclusion of said source in circuit with the wanted line, test means for said mechanism operative responsive to the idle condition of the wanted line to cause the operation of the actuating means and operative responsive to the busy condition of the wanted line to prevent the inclusion of said source in circuit with the wanted line, and means for applying said test means to a contact of the wanted line on selection thereof.

89. A telephone system including a plurality of telephone lines, a source of alternating current, switch contacts including a terminal of said source adapted when actuated to include said terminal and source in bridge circuit with a called line, an electrically controlled selective mechanism adapted to associate said contacts with any desired one of said lines, actuating means for said switch, and means at the sub-station of a called line to discontinue the inclusion of said source in circuit therewith.

90. A telephone system including a plurality of telephone lines, a source of calling current, a link circuit provided with con-

nection terminals, an electrically controlled selective mechanism adapted to associate said connection terminals with any desired one of said lines, means for intermittently connecting said source to said terminals, and means at the sub-station of a called line effective to discontinue the connection of said source to said terminals.

91. A telephone exchange system including a plurality of telephone lines, a source of alternating current, a link circuit provided with connection terminals, and electrically controlled selective mechanism adapted to associate said terminals with any desired one of said lines, means for automatically connecting said source to said terminals, and means at the sub-station of a called line effective to discontinue the connection of said source to said terminals.

92. A telephone system including a plurality of telephone lines, a main station, a source of calling current, a link circuit provided with connection terminals, and an electrically controlled selective mechanism at the main station adapted to associate said link circuit with any desired one of said lines, and main station self-acting means automatically effective responsive to the association of said link circuit with an idle one of said lines for intermittently connecting said source to said terminals.

93. A telephone system including a plurality of telephone lines, a source of calling current, a link circuit provided with connection terminals, an electrically controlled selective mechanism adapted to associate said link circuit with any desired one of said lines, means automatically effective responsive to the association of said link circuit with an idle one of said lines for intermittently connecting said source in circuit with said terminals, and means at the sub-station of the selected line effective to discontinue the connection of said source with said terminals.

94. A telephone system including a plurality of telephone lines each having multiple terminals, link circuits each provided with talking terminals adapted to engage said multiple terminals, electrically controlled selective mechanism adapted to associate any link circuit with any desired one of said lines, a source of alternating current, means automatically effective responsive to the association of a link circuit with an idle one of said lines for intermittently connecting said source in circuit with said talking terminals, and means at the sub-station of the selected line effective to discontinue the connection of said source with said terminals.

95. A telephone system including a plurality of telephone lines, a link circuit at a main station for interchangeably interconnecting any pair of said lines, an electrically

controlled selective mechanism adapted to associate said link circuit with any desired one of said lines, a ringing switch individual to said link circuit, a source of ringing current associated with the contacts of said switch, and means self-actuated only responsive to a selective movement of said mechanism for periodically actuating said switch.

96. A telephone system including a plurality of telephone lines, a source of calling current, a plurality of link circuits, electrically controlled selective mechanisms for associating said link circuits with any desired one of said line, a periodically actuated ringing switch for each link circuit, and a common source of energy, and means self-actuated upon only the selective operation of said selective mechanisms to automatically apply said source to actuate said ringing switches.

97. A telephone system including a plurality of telephone lines, a plurality of link circuits, an electrically controlled selective mechanism for each link circuit adapted to effect its association with any desired one of said lines, a source of calling current common to said link circuits, and means including a ringing switch individual to each link circuit for intermittently connecting said source in circuit with an idle called line automatically effective following the selection of said idle line independently of the time of connection of said source in circuit with any other called line.

98. A telephone system including a calling and wanted line, a trunk line, an electrically controlled selective mechanism adapted to connect said trunk line with the wanted line, a source of calling current, a switch individual to said trunk line adapted when actuated to connect said source intermittently in circuit with the wanted line, a test contact for the wanted line, a test relay for said mechanism, means for applying said test relay to said test contact on selection of the wanted line, and means controlled by said relay adapted to prevent the actuation of said switch in case said wanted line be busy.

99. A telephone system including a calling and a wanted line, a trunk line, an electrically controlled selective mechanism adapted to connect said trunk line with the wanted line, a source of calling current, a switch individual to said trunk line adapted when actuated to connect said source intermittently in circuit with the wanted line, a test contact for the wanted line, a test relay for said mechanism, means for applying said relay to said test contact on selection of the wanted line, and means controlled by said relay effective to cause the actuation of said switch in case said called line be idle.

100. A telephone system including a calling and a wanted line, an electrically controlled selective mechanism adapted to con-

nect with the wanted line, a source of calling current, a switch adapted when actuated to include said source in circuit with the wanted line through a line connecting portion of said mechanism, means individual to the selective mechanism for intermittently actuating said switch, and an electrical circuit closed on selection of an idle wanted line to render said actuating means effective.

101. A telephone system including a calling and a wanted line, a trunk line, an electrically controlled selective mechanism adapted to connect said trunk line with the wanted line, a source of calling current, a switch individual to said trunk line adapted when actuated to include said source intermittently in circuit with the wanted line, actuating means for said switch automatically effective responsive to the selection of an idle wanted line, a central source of talking current, an inductive winding adapted for inclusion in circuit between said source and the talking conductors of the wanted line, and means including said inductive winding to discontinue the connection of said source in circuit with the wanted line.

102. A telephone system including a calling and a called line, an electrically controlled selective mechanism adapted to connect with the called line, a source of calling current, a switch adapted when actuated to connect said source in circuit with the called line, means at the sub-station of the called line to discontinue the connection of said source, and means automatically effective at the end of a predetermined period to discontinue the connection of said source in case the connection of said source be not discontinued by said means at the sub-station.

103. In an automatic telephone system, the combination with a plurality of normally open instrument circuits, each provided with signaling devices, a connector switch mechanism serving to connect one, a calling circuit, with another a called circuit, and devices for operating said switch mechanism to select and test a desired called circuit, of a source of current supply for signaling purposes, a relay operated upon the test of an idle called circuit to automatically apply said current to the selected called instrument circuit, means for interrupting the flow of said current to cause alternating periods of activity and quiescence in the signaling devices of the called circuit and a relay connected to said called circuit during the quiescent periods which is adapted to be actuated when said instrument circuit is closed to remove the signaling current.

104. In an automatic telephone system, the combination with a plurality of normally open instrument circuits, each provided with signaling devices, a connector switch mechanism serving to connect one, a calling circuit, with another a called circuit, and de-

5 vices for operating said switch mechanism to select and test a desired called circuit, of a source of current supply for signaling purposes comprising a circuit which is normally disconnected from the instrument circuits, and a ringing switch which is operated intermittently following selection and test of an idle called circuit to intermittently connect the signaling circuit to the called instrument circuit.

10 105. A telephone system including a plurality of telephone lines, a source of calling current, a link circuit provided with connection terminals, an electrically controlled selective mechanism adapted to select and test any desired one of said lines, and means automatically effective responsive to the selection and test of an idle one of said lines for intermittently connecting said source to said terminals.

15 106. A telephone system including a plurality of telephone lines, a source of calling current, a link circuit provided with connection terminals adapted to connect with said lines, an electrically controlled selective mechanism adapted to select and test any desired one of said lines, means automatically effective responsive to the selection and test of an idle one of said lines for intermittently connecting said source in circuit with said terminals, and means at the sub-station of the selected line effective to discontinue the connection of said source with said terminals.

20 107. A telephone system including a plurality of telephone lines each having multiple terminals, link circuits each provided with talking terminals adapted to engage said multiple terminals, electrically controlled selective mechanism adapted to select and test any desired one of said lines, a source of alternating current means automatically effective responsive to the selection and test of an idle one of said lines for intermittently connecting said source in circuit with said talking terminals, and means at the sub-station of the selected line effective to discontinue the connection of said source with said terminals.

25 108. In a telephone system, a called subscriber's line, an automatic connector switch for connection therewith, means responsive to such connection for automatically intermittently applying signalling current to the said called line, and means responsive to the removal of the receiver at the called subscriber's sub-station for automatically discontinuing said application of the said signalling current to said line.

30 109. In a telephone system, a called subscriber's line, a sub-station thereon provided with a signal receiving device, an automatic connector switch for connection to said line, signalling means associated with said connector switch, means for intermittently ap-

35 plying said signalling means to the line of the said called subscriber to intermittently operate said signal receiving device, and means controlled by the response of the called subscriber for discontinuing said application of the signalling means to said called line.

40 110. In a telephone system, a calling subscriber's line, a called subscriber's line, directly controlled automatic switching apparatus including an automatic connector switch for connecting said calling and called lines in conversational circuit, signalling means associated with said connector switch, an automatic device for periodically connecting the said signalling means to the said called subscriber's line, a battery, means for connecting the said battery to the called subscriber's line between the said signalling periods, and means responsive to a flow of current from the said battery for stopping the periodic connecting of the said signalling means with the called subscriber's line.

45 111. A telephone exchange system comprising subscribers' lines, a trunk line, means for connecting a calling line therewith, another trunk line, both of said trunk lines having two conductors for conversational purposes, automatic switching mechanism for extending said trunk line to connection with the other said trunk line and for connecting said other trunk line with a wanted line, a central source of talking current, an inductive winding, said winding and said source of talking current being in circuit with but one of said conductors of said other trunk line, and restoring means for said mechanism controlled by said winding.

50 112. A telephone exchange system comprising subscribers' lines, a link circuit, means for connecting a calling line therewith, a trunk line, automatic switching mechanism for extending said link circuit to connection with said trunk line, and for connecting said trunk line with a wanted line, a central source of current associated with a talking conductor of said trunk line, an inductive winding in a circuit of said source and conductor under control of the wanted line, and restoring means for said mechanism controlled by said winding.

55 113. A telephone exchange system comprising subscribers' lines, a link circuit, means for connecting a calling line therewith, a trunk line, automatic switching mechanism for extending said link circuit to connection with said trunk line, other automatic switching mechanism for connecting said trunk line with a wanted line, a central source of current associated with a talking conductor of said trunk line, an inductive winding in a circuit of source and conductor under control of the wanted line, and restoring means for said other mechanism controlled by said winding.

114. In a telephone exchange system comprising subscribers' lines, link circuits, selecting mechanism automatically effective upon the initiation of a call over a calling line for connecting said line with a link circuit, automatic switching mechanism for extending said link circuit to connection with a wanted line, restoring means for said selecting mechanism, means to prevent the operation of the switching mechanism in case the calling line is in condition to initiate a call during the restoration of the selecting mechanism. 65
115. A telephone exchange system comprising subscribers' lines, an automatic selecting mechanism associated with a calling line, an automatic connecting mechanism common to a plurality of said selecting mechanisms associated with a wanted line, talking conductors extending between said mechanisms, restoring means for said mechanism and means jointly controlled by said calling and wanted lines for controlling said restoring means. 70
116. A telephone exchange system comprising subscribers' lines, an automatic selecting mechanism associated with a calling line, an automatic connecting mechanism common to a plurality of said selecting mechanisms associated with a wanted line, talking conductors extending between said mechanisms, restoring means for said mechanisms and means under control of said wanted line for controlling said restoring means. 75
117. A telephone exchange system comprising subscribers' lines, an automatic selecting mechanism associated with a calling line, an automatic connecting mechanism common to a plurality of said selecting mechanisms associated with a wanted line, talking conductors extending between said mechanisms, restoring means for said mechanisms and means under control of said wanted line for disabling restoration of said connecting mechanisms. 80
118. A telephone exchange system comprising subscribers' lines, an automatic selecting mechanism associated with a calling line, an automatic connecting mechanism common to a plurality of said selecting mechanisms associated with a wanted line, a trunk line including talking conductors extending between said mechanisms, restoring means for said selecting mechanism under control of said calling line, and restoring means for said connecting mechanism under control of said wanted line. 85
119. A telephone exchange system comprising subscribers' lines, automatic selecting mechanism associated with a calling line, automatic connecting mechanism connected with a wanted line, talking conductors extending between said mechanisms, restoring means for said selecting mechanism, means for said selecting mechanism, means operable for restoring said connecting mechanism independent of said first mentioned restoring means, and means under control of said wanted line for disabling said means for restoring said connecting mechanism. 90
120. A telephone exchange system comprising subscribers' lines, automatic selecting mechanism associated with a calling line, automatic connecting mechanism associated with a wanted line, a trunk line including talking conductors extending between said mechanisms, means for restoring said selecting mechanism, and means for restoring said connecting mechanism controlled by said wanted line but not under control of said calling line. 95
121. A telephone exchange system comprising subscribers' lines, automatic selecting mechanism associated with a calling line, automatic connecting mechanism associated with a wanted line, a trunk line including talking conductors extending between said mechanisms, means for restoring said connecting mechanism, and means for restoring said selecting mechanism independently of the restoration of said connecting mechanism. 100
122. A telephone exchange system comprising subscribers' lines, automatic selecting mechanism associated with a calling line, a trunk line including talking conductors extending between said mechanisms, means for restoring said connecting mechanism, and means controlled by said calling line for restoring said selecting mechanism independently of the restoration of said connecting mechanism. 105
123. A telephone exchange system comprising a telephone line, a talking conductor therefor, a trunk line, means for connecting said telephone line with said trunk line, a second trunk line, automatic switching mechanism for connecting said trunk line with said second trunk line, a common source of talking current, a circuit of said source including said conductor, restoring means for said mechanism, and means actuated responsive to interruption of said circuit of said source for actuating said restoring means. 110
124. A telephone exchange system comprising a telephone line, a talking conductor therefor, a trunk line, a central source of current, means for connecting said telephone line with said trunk line, a second trunk line, automatic switching mechanism for establishing connection between said trunk line and said second trunk line, a circuit of said source including said talking conductor closed during continuance of said connection, restoring means for said mechanism, 115
- 125

and means responsive to interruption of said circuit of said source for actuating said restoring means.

125. A telephone exchange system comprising a telephone line, a pair of talking conductors therefor, a trunk line, a central source of current, means for connecting said telephone line with said trunk line, a second trunk line, automatic switching mechanism for connecting said trunk line with said second trunk line, a circuit of said source including said talking conductors in serial relation, restoring means for said mechanism, and means responsive to interruption of said circuit of said source for actuating said restoring means.

126. A telephone exchange system comprising a pair of subscribers' lines, a trunk line, a second trunk line, automatic switching mechanism for connecting said lines in circuit with the talking conductors of said trunk lines, a central source of current, a circuit of said source including serially related talking conductors of one of said lines, restoring means for said mechanism, and means responsive to interruption of said circuit of said source for actuating said restoring means.

127. A telephone exchange system comprising a pair of subscribers' lines, substitution microphones therefor, a trunk line, a second trunk line, automatic switching mechanism for connecting said lines in circuit with the talking conductors of said trunk lines, a common source of talking current, a circuit of said source including the microphone of one of said lines, restoring means for said mechanism, and means responsive to interruption of said circuit of said source for actuating said restoring means.

128. In a common battery automatic telephone exchange trunking system, a plurality of switches for extending connection from one point to another, said switches occurring in succession, and trunk lines extending from one switch to the other, and means whereby if any one of said switches encounters an open trunk-line all the switches so far involved will be automatically released.

129. In an automatic telephone exchange trunking system, a plurality of switches for extending connection from one point to another, said switches occurring in succession, and trunk-lines extending from one switch to the other, each of said trunk-lines including a trunk-release conductor, and means whereby if any one of said switches encounters a trunk-line the trunk-release conductor of which is open all the switches so far involved will be automatically released.

130. In an automatic telephone exchange trunking system, a plurality of switches for

establishing connection from one point to another, said switches occurring in succession and trunk-lines extending from one to the other, said trunk-lines including a trunk-release conductor, and means whereby if any one of said switches encounters an open trunk line all the switches so far involved will be automatically released.

131. In a telephone system, a plurality of automatic switches for use in extending a connection, means for successively operating said switches, trunk lines extending from one switch to another, and automatic means whereby if any switch seizes an open trunk line all of the switches so far involved in the connection are automatically released.

132. In automatic connective circuits and apparatus for telephone systems, a plurality of magnetically controlled connective means responding to relatively short current changes only, and magnetic control or shifting means for the circuit of the connective means responding to relatively long current changes only, with means to produce long and short changes in desired sequence, substantially as described.

133. In a telephone exchange system, an automatic switch and an auxiliary circuit changing switch associated therewith, electromagnetic means for operating each switch, the several magnets having different time constants, a circuit connection for the automatic switch magnet extending through contacts in the auxiliary switch, and means under the control of the calling subscriber for producing operating and control changes of different durations in the circuits of the magnets, substantially as described.

134. In a telephone system, an automatic switch with operating magnets, an auxiliary control or side switch therefor, also with operating magnets, the magnets of the main and auxiliary switches having different time constants, subscribers' lines, and means at the subscribers' stations for sending intermittent groups of line impulses to produce changes in the respective magnet circuits of proper duration and in proper sequence to affect the switches operatively, substantially as described.

135. In a telephone exchange system, a plurality of metallic line circuits, a number of automatic switches less than the number of line circuits for interconnecting the same, means to connect a calling line with an idle switch, means associated with each line when calling to produce in the metallic circuit current changes of different durations and grouped according to a predetermined code, local actuating circuits for each automatic switch, and auxiliary controlling means for the same associated with each switch, together with controlling magnets for the

switch and for the auxiliary means, having different time constants, whereby both the switch movement and its auxiliary control will be effected by and in response to the code impulses or current changes in the calling line.

136. In a telephone exchange system, a plurality of metallic or two-wire line circuits, a number of automatic switches less than the number of lines, for purposes of interconnection, means to connect a calling line with an idle switch, auxiliary apparatus including means for signaling a called subscriber, associated with each switch, local branch control circuits for each switch and its auxiliary apparatus, electromagnets controlling each switch and its local branch circuits and auxiliary apparatus respectively, said electromagnets having different time constants, and a sending device associated with a line when calling, having selective setting means for predetermining a number, and means automatically actuated thereby adapted to produce current changes of varying duration in the line circuit in accordance with the code indication for the number selected, whereby the operation of the automatic switch, the shifting of its local circuits, and the control of the auxiliary apparatus, will all be effected in proper sequence so as to select, connect with, and signal, the line wanted.

137. In a telephone exchange system, a metallic line circuit, an automatic selective switch normally disconnected therefrom and containing the terminals of other lines, auxiliary means associated with said switch for testing and for signaling a line wanted, local actuating circuits for each switch, controlling electromagnets for the switch and for the local circuits and auxiliary devices respectively, said magnets having different time constants, means for connecting the line when calling with the switch, and a sender associated with the line when calling adapted to produce current changes therein of varying durations, and according to a code arrangement.

138. In a telephone exchange system, central automatic switching means having actuating circuits and auxiliary apparatus including testing and ringing means, and a side switch controlling the same, controlling electromagnets for the switch and for its auxiliary elements, having different time constants, a two-wire metallic line circuit connected to the switch, and means to produce current changes therein of different duration to effect switch movements and auxiliary control respectively.

139. A telephone exchange system comprising a circuit including a talking conductor, associated automatic switch mechanism having waiting contacts divided into groups and a cooperating moving contact, means

outside of said mechanism for rendering some of said waiting contacts busy, means for determining adjustment of said moving contact to a desired group of waiting contacts in response to variations of current transmitted over said conductor means for initiating adjustment of said moving contact in search of an idle contact in that group in response to another current variation transmitted over said conductor and means for effecting movement of said moving contact in such search and stopping it only when an idle waiting contact is reached.

140. In a telephone exchange system, a plurality of metallic line circuits, and means for interconnecting them comprising a number of automatic selective switches and sequential link circuits, electromagnetic actuating and controlling means associated with each link, the electromagnets of said actuating and controlling means having different time constants, and means associated with a line when calling to produce groups of current changes therein, each group composed of changes of different durations, whereby the actuating and controlling electromagnets in the several links required to build up a connection may be effectively energized in proper sequence.

141. A telephone exchange system comprising a telephone line extended from a central office to a distant point, a source of current in circuit with said line, manually controlled means at said distant point for interrupting the circuit of the line, other telephone lines, an electrically controlled switch at the central office for establishing connection between said line and said other lines, active contacts, for said switch constituting terminals for said line, passive contacts for said switch constituting terminals for said other lines, restoring means for said switch, means responsive to short interruptions of the circuit of said line for causing a primary operation of said switch, and means responsive after connection is established with a desired line whereby a long interruption of the circuit of said line will cause a secondary operation of said switch.

142. A telephone exchange system comprising a telephone circuit including a talking conductor, associated automatic switch mechanism having waiting contacts divided into groups and a cooperating moving contact, means outside of said mechanism for rendering some of said waiting contacts busy, means for determining adjustment of said moving contact to a desired group of waiting contacts in response to successive intermittent current variations transmitted over said talking conductor, means actuated responsive to interruption of said variations for initiating adjustment of said moving contact in search of an idle contact in that group, and means for effecting movement

of said moving contact in such search and stopping it only when an idle waiting contact is reached.

143. A telephone exchange system comprising a telephone line extending from a central office to a distant point, a source of current in circuit with said line, manually controlled means at said distant point for interrupting the circuit of the line, other telephone lines, an electrically controlled switch at the central office for establishing connection between said line and said other lines, active contacts for said switch constituting terminals for said line, passive contacts for said switch constituting terminals for said other lines, active contacts for said switch constituting terminals for said line, passive contacts for said switch constituting terminals for said other lines, restoring means for said switch, controlling means for said switch responsive to short interruptions of the circuit of said line, selecting means for said switch normally responsive to said controlling means whereby said active contacts are brought into relation with any group of passive contacts, engaging means for said switch whereby said active contacts are brought into engagement with said passive contacts, and means responsive to a long interruption directly succeeding a short interruption of the circuit of said line for rendering said selecting means unresponsive to said controlling means and for causing an automatic operation of said engaging means.

144. A telephone exchange system comprising a telephone line extending from a central office to a distant point, a source of current in circuit with said line, manually controlled means at said distant point for interrupting the circuit of the line, other telephone lines, an electrically controlled switch at the central office for establishing connection between said line and said other lines, active contacts for said switch constituting terminals for said line, passive contacts for said switch constituting terminals for said other lines, restoring means for said switch, controlling means for said switch responsive to short interruptions of the circuit of said line, selective means for said switch normally responsive to said controlling means whereby said active contacts are brought into relation with any group of passive contacts, engaging means for said switch whereby said active contacts are brought into engagement with said passive contacts, means responsive to a long interruption directly succeeding a short interruption of the circuit of said line for causing an automatic operation of said engaging means, and means for arresting the operation of said engaging means.

145. A telephone exchange system comprising a telephone line extending from a central office to a distant point, a source of current in circuit with said line, manually controlled means at said distant point for interrupting the circuit of the line, other

telephone lines, an electrically controlled switch at the central office for establishing connection between said line and said other lines, active contacts for said switch constituting terminals for said line, passive contacts for said switch constituting terminals for said other lines, restoring means for said switch, means responsive to short interruptions of the circuit of said line for causing a primary operation of said switch, and means responsive to a long interruption directly succeeding a short interruption of the circuit of said line for connecting the talking circuit of said line with the talking circuit of an idle other line.

146. A telephone exchange system comprising a telephone line extending from a central office to a distant point, a source of current in circuit with said line, manually controlled means at said distant point for interrupting the circuit of the line, other telephone lines, an electrically controlled switch at the central office for establishing connection between said line and said other lines, active contacts for said switch constituting terminals for said line, passive contacts for said switch constituting terminals for said other lines, restoring means for said switch, means responsive to short interruptions of the circuit of said line for causing a primary operation of said switch, and means responsive to a long interruption directly succeeding a short interruption of the circuit of said line for connecting a source of signaling current to the line limb of an idle other line.

147. A telephone exchange system comprising a telephone line extending from a central office to a distant point, a source of current in circuit with said line, manually controlled means at said distant point for interrupting the circuit of the line, other telephone lines, an electrically controlled switch at the central office for establishing connection between said line and said other lines, active contacts for said switch constituting terminals for said line, passive contacts for said switch constituting terminals for said other lines, restoring means for said switch, means responsive to short interruptions of the circuit of said line for causing a primary operation of said switch, and means responsive to a long interruption directly succeeding a short interruption of the circuit of said line for connecting the talking circuit of said line with the talking circuit of an idle other line and for connecting a source of signaling current to the line limb of an idle other line.

148. A telephone exchange system comprising a telephone line extending from a central office to a distant point, a source of current in circuit with said line, manually controlled means at said distant point for interrupting the circuit of the line, other telephone lines, an electrically controlled switch

- at the central office for establishing connection between said line and said other lines, active contacts for said switch constituting terminals for said line, passive contacts for said switch constituting terminals for said other lines, restoring means for said switch, means responsive to short interruptions of the circuit of said line for causing a primary operation of said switch, a controlling relay for said switch responsive only to long interruptions of the circuit of said line, and means controlled by said relay for causing the operation of said restoring means.
149. In a telephone system, the combination of telephone lines, a plurality of connector switches less in number than said telephone lines, locking means dependent upon the use of said connector switches for connecting purposes to hold the same in an off-normal position, automatic means for restoring said connector switches when thrown into an off-normal position while idle, and means for supplying current over the telephone lines to operate said switches, and for talking purposes also.
150. In a telephone system, the combination of trunk-lines, a first-selector switch adapted to select idle trunk-lines, locking means dependent upon the use of said selector switch for connecting purposes to hold the same in an off-normal position, automatic means for restoring said first-selector when thrown into an off-normal position while idle, and means for supplying current over the subscribers' lines to operate said first-selector switch, and for talking purposes also.
151. A telephone exchange system comprising subscribers' lines, groups of trunk lines terminating in corresponding groups of waiting contacts, a link circuit, means for automatically connecting said link circuit with any calling line, a traveling terminal for said link circuit, automatic mechanism directly controlled for moving said terminal to a group of waiting contacts corresponding to an elected group of trunk lines and automatically controlled for moving said traveling terminal into engagement with a waiting contact corresponding to a trunk line in the elected group, and means for connecting said trunk line to the line of a called subscriber.
152. A telephone exchange system comprising a group of subscribers' lines, a lesser group of link circuits adapted for simultaneous independent association therewith, groups of trunk lines terminating in corresponding groups of waiting contacts, means for automatically connecting any link circuit with any calling line, a traveling terminal for each link circuit, automatic mechanism directly controlled for moving any traveling terminal to a group of waiting contacts corresponding to an elected group of trunk lines and automatically controlled for moving said traveling terminal into engagement with a waiting contact corresponding to a trunk line in the elected group, and means for connecting said trunk line to the line of a called subscriber.
153. A telephone exchange system comprising groups of subscribers' lines, lesser groups of link circuits for said line groups, groups of trunk lines corresponding to said line groups and terminating in corresponding groups of waiting contacts, means for automatically connecting any link circuit with any calling line of a related line group, a traveling terminal for each link circuit, automatic mechanism directly controlled for moving any traveling terminal to a group of waiting contacts corresponding to an elected group of trunk lines and automatically controlled for moving said traveling terminal into engagement with a waiting contact corresponding to an idle trunk line in the elected group, and means for connecting said idle trunk line to the line of a called subscriber in the corresponding line group.
154. A telephone system including a subscriber's telephone line, electrically controlled switching means associated with said line, and means under the control of the subscriber for establishing a condition such as to cause said switching means to establish a definite connection and for returning said switching means to normal in case said condition is removed before said connection has been established.
155. A telephone exchange system comprising a group of subscribers' lines arranged in sub-groups, groups of waiting contacts corresponding to said sub-groups, a link circuit having a traveling terminal, automatic switching mechanism for connecting said link circuit to a calling line in any sub-group comprising means primarily adjusted for advancing said traveling terminal to the group of contacts corresponding to the sub-group and secondarily adjusted for advancing said terminal to engagement with the contact in said group corresponding to said calling line, and means for connecting said link circuit to a wanted line.
156. A telephone exchange system comprising a group of subscribers' lines arranged in sub-groups, groups of waiting contacts corresponding to said sub-groups, a link circuit having a traveling terminal, automatic switching mechanism actuated responsive to the initiation of a call by a line in any sub-group for connecting said link circuit to said line comprising means primarily adjusted for advancing said travel-

- ing terminal to the group of contacts corresponding to the sub-group and secondarily adjusted for advancing said terminal to engagement with the contact in said group corresponding to said calling line, and means for connecting said link circuit to a wanted line.
157. A telephone exchange system comprising a group of subscribers' lines arranged in 10 sub-groups, groups of waiting contacts corresponding to said sub-groups, a group of link circuits each having a traveling terminal, means for isolating an idle one of said link circuits, automatic switching mechanism for connecting said isolated link circuit to a calling line in any sub-group comprising means primarily adjusted for advancing said traveling terminal to the group of contacts corresponding to the sub-group 20 and secondarily adjusted for advancing said terminal to engagement with the contact in said group corresponding to said calling line, and means for preventing the connection of a second one of said link circuits to 25 the connected calling line.
158. A telephone-exchange formed of one or more exchange-sections, each exchange-section comprising a plurality of sub-sections upon which telephone-lines terminate, 30 loop-circuits each having two terminal connectors and extending between one of the sub-sections and an intermediate sub-section of the same exchange-section and adapted to be connected with a telephone-line to extend 35 the circuit to said intermediate sub-section, trunk-lines extending between a second sub-section of the same or other exchange-sections and said intermediate sub-section and adapted to be connected with said telephone 40 line to extend the circuit from said auxiliary sub-section to said second sub-section, and means at each of said intermediate and second sub-sections operable responsive to a variable series of electrical impulses in a 45 calling line for uniting one of the loop circuits with an idle one of the trunk lines and said idle trunk line with a wanted line.
159. A telephone exchange system comprising telephone lines terminating in 50 groups of waiting contacts, other telephone lines also terminating in groups of waiting contacts, a link circuit provided with a traveling terminal at each of its two extremities, automatic switching mechanism 55 for connecting said link circuit to any one of said first mentioned telephone lines comprising means primarily adjusted for advancing one of said traveling terminals to the group of contacts and secondarily adjusted 60 for advancing said terminal to engagement with the contact in the group corresponding to such line, and automatic switching mechanism for connecting said link circuit to any one of said other telephone lines by moving the other of said 65 traveling terminals to the groups of contacts and to engagement with the contact in the group corresponding to such other telephone line.
160. A telephone exchange system comprising 70 telephone lines terminating in groups of waiting contacts, other telephone lines also terminating in groups of waiting contacts, a group of link circuits each provided with a traveling terminal at each of its extremities, means for isolating an idle one of said link circuits, automatic switching mechanism for connecting the isolated link circuit to any one of said first mentioned telephone lines comprising means primarily 75 adjusted for advancing one of its traveling terminals to the group of contacts and secondarily adjusted for advancing said terminal to engagement with the contact in the group corresponding to such line, automatic switching mechanism for connecting said isolated link circuit to any one of said other telephone lines comprising means primarily 80 adjusted for advancing the other of its traveling terminals to the group of contacts and secondarily adjusted for advancing said other terminal to engagement with the contact in the group corresponding to such other telephone line, and means to prevent the connection of a second link circuit of said group 85 with a so-connected telephone line.
161. A telephone exchange system comprising subscribers' lines, trunk lines, a link circuit for associating calling lines with said 90 trunk lines, a traveling terminal at each end of said link circuit, groups of waiting contacts corresponding to said subscribers' lines, groups of waiting contacts corresponding to said trunk lines, means for connecting said trunk lines to wanted lines, automatic 95 switching mechanism for connecting said link circuit to a calling line comprising means primarily adjusted for advancing one of said traveling terminals to the group of contacts and secondarily adjusted for advancing said terminal to engagement with the contact in the group corresponding to said calling line, and automatic switching 100 mechanism comprising means primarily adjusted for advancing the other of said traveling terminals to an elected group of trunk line contacts and secondarily adjusted for advancing said other terminal to engagement with the contact of an idle trunk line 105 in said elected group.
162. In a telephone exchange system, means for distributing calls comprising primary and secondary selector switches connected in pairs, magnets for directly actuating said secondary selector switches responsive to a variable series of electrical impulses in a calling line, lines connected to multiple terminals in the primary selectors, connective central office circuits divided into 110 groups leading to said other selector 115
163. In a telephone exchange system, means for distributing calls comprising primary and secondary selector switches connected in pairs, magnets for directly actuating said secondary selector switches responsive to a variable series of electrical impulses in a calling line, lines connected to multiple terminals in the primary selectors, connective central office circuits divided into groups leading to said other selector 115

switches, and each of said groups multiplied to terminals of secondary selectors in a corresponding group.

163. In a telephone exchange system, 5 means for distributing calls comprising automatic primary and secondary selector switches, line terminals in the primary switches, other selector switches, terminals of said other selector switches in the secondary selector switches, a switching member for each primary selector switch with an electromagnet to actuate the same, and means controlled by the calling line to energize said magnet, together with a switching member for each secondary selector with a controlling electromagnet for directively adjusting the same responsive to a variable series of electrical impulses in the calling line.
164. In a telephone exchange system, a 20 plurality of lines, connective central office circuits terminating in selector switches therefor, means for distributing calls comprising primary and secondary selectors normally connected in pairs independently 25 of the lines and connective central office circuits, and means including a magnet actuated responsive to a variable series of electrical impulses in a calling line to operate said selectors to effect through their respective pairs of primary and secondary selectors a combination between any calling line and any connective circuit associated with the selectors.

165. A telephone exchange system comprising subscribers' lines, groups of trunk lines terminating in corresponding groups of waiting contacts, a link circuit, switching means coupled to one end of said link circuit for connecting with a calling line, a 35 traveling terminal coupled to the other end of said link circuit, automatic mechanism directly controlled for moving said terminal to a group of waiting contacts corresponding to an elected group of trunk lines and automatically controlled for moving said traveling terminal into engagement with a waiting contact corresponding to a trunk line in the elected groups, and means for connecting said trunk line to the line of a called subscriber.

166. A telephone exchange system comprising a group of subscribers' lines, a lesser group of link circuits adapted for simultaneous independent association therewith, 50 groups of trunk lines terminating in corresponding groups of waiting contacts, switching means coupled to one end of each link circuit for connecting with any calling line, a traveling terminal coupled to the other end of each link circuit, automatic mechanism directly controlled for moving any traveling terminal to a group of waiting contacts corresponding to an elected group of trunk lines and automatically controlled 55 for moving said traveling terminal into en-

gagement with a waiting contact corresponding to a trunk line in the elected group, means for connecting said trunk line to the line of a called subscriber, and means for preventing the association of a second link 70 circuit with said trunk line during said engagement.

167. A telephone exchange system comprising groups of subscribers' lines, lesser groups of link circuits for said line groups, 75 groups of trunk lines corresponding to said line groups and terminating in corresponding groups of waiting contacts, switching means coupled to one end of each link circuit for connecting with any calling line of 80 a related line group, a traveling terminal coupled to the other end of each link circuit, automatic mechanism directly controlled for moving any traveling terminal to a group of waiting contacts corresponding to an elected group of trunk lines and automatically controlled for moving said traveling terminal into engagement with a waiting contact corresponding to an idle trunk line 85 in the elected group, and means for connecting said idle trunk line to the line of a called subscriber in the corresponding line group.

168. A telephone exchange system, comprising a calling line and a wanted line, an impulse sending device, a link circuit, means for connecting the calling line to the link circuit, numerical registering means responsive to current impulses received over the link circuit from said sending device, and switching means operated in accordance with the adjustment of said numerical registering means responsive to said current impulses to connect said link circuit to said wanted line.

169. A telephone exchange system, comprising a calling line and a wanted line, a link circuit, means for connecting said link circuit to said calling line, an impulse sending device, numerical registering means responsive to current impulses received over the link circuit from said sending device, means for connecting said sending device to said numerical registering means to set the same in accordance with the designation of said wanted line, and switching means controlled by the adjustment of said numerical registering means in response to said impulse sending device to connect the link circuit to said wanted line.

170. A telephone exchange system, comprising a calling line and a wanted line, a link circuit, means for connecting said link circuit to said calling line, an impulse sending device, a numerical register comprising an element having a definite initial position and means for moving said element to a predetermined position in response to current impulses received over said link circuit from said sending device, switching means for connecting said link circuit to the

wanted line dependent upon the adjustment of said numerical register, and means for restoring said element of said register to its initial position.

- 5 171. A telephone exchange system, comprising a calling line, and a called line, a link circuit, means for connecting said link circuit to said calling line, an impulse sending device, numerical registering means associated with said link circuit responsive to current impulses from said sending device received over said link circuit, a second link circuit, switching means dependent upon the adjustment of said numerical registering means for connecting said link circuit to said second link circuit, numerical registering means associated with said second link circuit responsive to current impulses from said sending device, and switching means dependent upon the adjustment of said last mentioned numerical registering means for connecting said second link circuit to the called line.

- 25 172. In a telephone exchange system, the combination of an automatic switch, a plurality of lines arranged in groups in said switch, identifying mechanism comprising a plurality of magnets, one for each of said groups, a movable member controlled by each magnet, means for energizing any of said magnets, the energizing of any magnet serving to stop the operation of the movable member to identify the group of lines where in a call is originated, and means for operating said switch to select the line in the group corresponding to the operated magnet.

- 35 173. In a telephone exchange system, the combination of an automatic switch, a line appearing in said switch, other lines arranged in groups appearing in said switch, an identifying mechanism comprising a plurality of magnets one for each of said groups, another group of magnets each serving a different line in said groups, movable members, one for each group of magnets, means for energizing the magnets individually to any of said groups for controlling the associating movable member, means for energizing the magnet serving a particular line in such group for controlling its associated movable member, means controlled by the actuated members for identifying the particular group of lines and for identifying the particular line in said group, and means responsive to the actuation of the identifying means to operate said switch to extend a connection from the identified line to another line.

- 40 174. In a telephone exchange system the combination of a line, a plurality of other lines, an automatic switch for interconnecting said first line with said other lines, a mechanism for identifying each of said other lines, means for operating said mechanism to identify a desired one of said other lines,

means for operating said switch to establish a connection between said first line and the identified line, a second automatic switch for further extending said connection, a sending device and registering means controlled by said sending device for determining the operation of said second automatic switch.

50 175. In a telephone exchange system the combination of a line, a plurality of other lines, an automatic switch for interconnecting said first line with said other lines, a mechanism for identifying each of said other lines, means for operating said mechanism to identify a desired one of said other lines, means for operating said switch to establish a connection between said first line and the identified line, a second automatic switch for further extending said connection, a variable operable sending device and registering means controlled in accordance with the setting of said sending device for determining the operation of said second switch.

55 176. In a telephone exchange system the combination of a line, a plurality of other lines, an automatic switch for interconnecting said first line with said other lines, an identifying mechanism including a plurality of magnets, one for each of said other lines, means for operating one of said magnets to identify the corresponding line, means for operating said switch to establish a connection between said first line and the line identified, a second automatic switch for further extending said connection, a sending device, and registering means controlled by said sending device for determining the operation of said second switch.

60 177. A telephone exchange system comprising subscribers' lines divided into a plurality of groups, an automatic trunking switch common to all of the subscribers' lines in all of said groups, said switch being movable to select divisions of the exchange and movable to connect with an idle trunk-line and adapted to perform a trunking operation in accordance with the first digit of any called number, and suitable means for trunking and completing the connection in accordance with the other digits of the called number.

65 178. In a telephone system, a plurality of automatic trunking switches each having only a single level of terminals, a plurality of electrical circuits for communication purposes a first selector, and means for successively operating said switches to extend a communication circuit from one of said circuits to said first selector.

70 179. In a telephone system, the combination with a plurality of telephone lines, a plurality of first selectors, means for interconnecting and calling one of said lines with an idle first selector, means for controlling

5 said selectors directively in accordance with the first digit of any call number, a switch for selecting an idle interconnecting means operated under the control of calling apparatus on one of the said lines.

10 180. In a telephone system, a train of automatic directively movable switches operable in accordance with all the digits of a called number for extending a connection to a called line, a secondary non-directive 50 trunking switch for extending connection to the first switch in said train, and a primary non-directive trunking switch controlling the extension of the calling line to said secondary switch.

15 181. In a telephone exchange system, a link circuit calling and called lines, a sender for transmitting impulses, an automatic switch, controlling means responsive to impulses transmitted by said sender to determine in advance the position to be assumed by said automatic switch to extend a connection from the calling to the called line, said impulses being received over said link circuit under the control of apparatus at the subscriber's station to select a called line to be connected to the calling line through talking strands of said link circuit.

20 182. In a telephone exchange system, a link circuit, a sender for transmitting impulses, controlling means responsive to said impulses, an automatic switch, said controlling means determining in advance the position to be assumed by said automatic switch, said impulses being received over said link circuit under the control of apparatus at the subscriber's station to select a called line to be connected to the calling line through talking strands of said link circuit.

25 183. In a telephone exchange system, a link circuit, a sender for transmitting impulses, electrically operated controlling means responsive to the impulses transmitted by said sender, mechanically operated control-

30 ling means, an automatic switch, said mechanically operated controlling means governed by said electrically operated controlling means to determine the position to be assumed by said automatic switch, said impulses being received over said link circuit under the control of apparatus at the subscriber's station to select a called line to be connected to the calling line through talking strands of said link circuit. 55

35 184. In a telephone exchange system a link circuit, a calling and a called line, a sender for transmitting impulses, an automatic switch, means for automatically connecting the calling line to said automatic switch, controlling means responsive to impulses transmitted by said sender to determine in advance the position to be assumed by said automatic switch to extend a connection from the calling to the called line, 60 said impulses being received over said link circuit under the control of apparatus at the subscriber's station to select a called line to be connected to the calling line through talking strands of said link circuit. 65

40 185. In a telephone exchange system, a link circuit, a calling and a called line, a sender for transmitting impulses, an automatic switch, means for automatically connecting the calling line to said automatic 70 switch, registers responsive to the impulses transmitted by said sender to determine the position to be assumed by said automatic switch to extend a connection from the calling to the called line, said impulses being received over said link circuit under the control of apparatus at the subscriber's station to select a called line to be connected to the calling line through talking strands of said link circuit. 75

45 80 Signed at New York, in the county of New York and State of New York, this twenty-sixth day of July nineteen hundred and four.

85 ERNEST AUGUST FALLER.
